APPARATUS FOR AND A METHOD OF REVISING TYPE IN COLUMNAR FORM

James S. Schwartz, Chicago, and Gunnard E. Stark, Lake Forest, Ill., assignors to R. R. Donnelley & Sons Company, a corporation of Delaware

Filed Sept. 11, 1957, Ser. No. 683,338

38 Claims. (Cl. 276—34)

This invention relates to apparatus for and a method of revising type in columnar form.

There are certain types of printing work in which type set in columnar form must be periodically revised by the removal of certain of the cast type slugs which are included in the columns. Such an operation naturally shortens each column from which a line is removed, and requires a reorganization of successive columns into new columns of equal length. In some cases material set in, for example, five-column pages must be reset in four columns. The present invention contemplates the provision of apparatus for and a method of reorganizing type into pages containing a different number of columns, and at the same time removing predetermined lines of type from the columns if desired.

A typical large scale printing operation in which such revision of set type must be performed is in the preparation for printing the subscriber's telephone directory. Columns of type for printing telephone directories are retained in made up form at all times, because a substantial part of the telephone directory must be reprinted every few days to provide the information operators with up-to-date listings. When a new or revised listing comes to the printer, the listing is set up on a type casting machine and is either added to the existing material at the proper position or is substituted for a listing which it supersedes. Discontinued listings must be removed from the page forms. Changes in listings are printed promptly from the set type and sent to the information operators of the telephone company.

To simplify the handling of the telephone directory by the information operators, they are provided with books in which the pages contain more columns, and longer columns, than are found in the directory for public distribution. In addition, the information directories are provided at intervals in each column with "eye catchers," which are either bold faced initials or a bold face name to break down the listings in each column into groups which may be readily scanned by the operator searching for a particular listing, or a line rule to show a new or revised testing.

When it is time to make up the subscribers' directory, the set type which has been held and revised throughout the year for printing the information operators' directories is reorganized, commonly from 5 columns per page to 4 columns per page, each column is shortened, and the "eye catchers" are removed from each column.

The principal object of the present invention, therefore, is to provide apparatus for converting columns of a given length into columns of a different length, reorganizing the columns from 5 side by side to 4 side by side, and removing predetermined lines in the process. The apparatus likewise removes column spacers of one length and inserts spacers of a different length.

A further object of the invention is to feed type one column at a time to apparatus for removing predetermined lines of type from the column.

Yet another object of the invention is to sever from

the type which has passed through the line removing apparatus a new column length which contains a desired number of lines.

Yet another object of the invention is to provide apparatus which senses when a multiple line listing will be divided during the operation of severing a column length, so that an operator may reorganize the lines to keep the multiple line listing in a single column.

Yet another object of the invention is to provide apparatus which automatically pulls out from between the set-up columns of type the column spacers which are used in the printing of the information operator's book, and inserts between the new column lengths, column spacers of suitable length.

Yet another object of the invention is to provide apparatus which may be run by a single operator, and which substantially eliminates the possibility of hand injury to the operator.

For convenience in describing and claiming the apparatus and method, the term, "retainable lines" will be used to refer to the lines in a column which are used in the printing of the directory for public distribution; and the term, "pre-determined removable lines" will be used to refer to the "eye catchers" and the like which must be removed from the columns before the public book is printed. Ordinarily, both are composite lines of type in the form of a type slug. A "line of type" as used herein includes line spacers, line rules, and other printing components not ordinarily included within the definition of "type" as used in the art.

The invention is illustrated in a preferred embodiment in the accompanying drawings, in which:

Figs. 27 thru 38 are fragmentary plan views of the machine shown in Fig. 1, illustrating several consecutive steps of the sequence of operations in revising type forms used for printing pages of the telephone information operators' directory and converting the type to forms for use in preparing subscribers' telephone directories;

Fig. 39 is a diagram illustrating the electric circuits for the machine; and

Fig. 40 is a diagram illustrating the fluid circuits for the machine, and also illustrating diagrammatically the arrangement of limit switches included in the electric circuit.

In general

Referring now to the drawings, and particularly to Fig. 1, the invention is illustrated in connection with a semi-automatic type form revising and composing apparatus which includes a supporting table A including a planar table top 10 on which all of the mechanisms of the apparatus are supported. Preferably, the table top is inclined downwardly from right to left, as viewed in Figs. 1 and 1a, to aid in the proper movement of the type slugs.

Generally, the table top 10 includes a supply or infeed area I for supporting and guiding a type form utilized in printing a page of the information directory. Alongside the infeed area I, there is a processing alley, generally designated II including an infeed end IIa, an outfeed end IIb, and an intermediate processing area IIc, along which columns of type from the original type form are moved for revising. Alongside the outfeed end of the processing alley, there is an outfeed or composing area III into which columns of a revised length are moved from the processing alley and arranged in side by side relationship to provide a revised type form for use in printing a page of a subscribers' telephone directory.

Movement of the type through the apparatus is illustrated in the sequence diagrams of Figs. 27-38, and will be described in considerable detail later. In general, the type handled by the apparatus is in columnar form consisting of a plurality of lines of type arranged side-

by-side on edge. As illustrated in Fig. 27, for example, the type form utilized in printing information directories includes 5 columns of type of predetermined length, numbered 1 to 5, side-by-side with column spacers 11 positioned between adjacent columns. The type form illustrated in Fig. 27 is moved laterally in the infeed area by an infeed mechanism IV which is powered by a hydraulic cylinder A to successively position the columns of type in the infeed end of the processing alley. As 10 columns are successively positioned in the processing alley, they are moved longitudinally along the alley into the revising area by a column feed V powered by a hydraulic cylinder B. In the revising area the retainable lines in a column are clamped in position by a clamping mechanism VI powered by a cylinder C (Fig. 9), and solenoid means C1; and the removable lines in the column are lifted to an area above the retainable lines by a stripping mechanism VII powered by a cylinder D (Fig. 9). The retainable lines are then released and the column feed V moves the column to the outfeed end of the processing alley. As the columns are moved from the infeed end of the processing alley to the processing area, the column spacers 11 are removed by the column feed mechanism.

25 In the outfeed end of the processing alley, columns of the revised length are severed from the columnar type in the alley by an outfeed mechanism IX which is powered by a hydraulic cylinder E to push such column lengths laterally from the alley into the composing area. 30 The lead line of type in the processing alley following the column length to be severed is sensed by a sensing mechanism VII to determine when such a line has no type at one margin, in order to avoid separation of multiple line listings. After the severed column length is 35 pushed into the composing area, a column spacer of the revised form length is inserted between the severed column length and processing alley by a spacer feed mechanism X which is powered by a cylinder F.

Referring now to Fig. 1a, the table top 10 may be 40 supported in an inclined position by any suitable means, preferably including table legs 12 and reinforcing members 13 as illustrated, suitably connected together and connected to the table top so as to form a movable unitary structure. The table top 10 is preferably inclined from 45 the infeed end to the outfeed end at an angle of about 5°, as illustrated.

Referring particularly to Figs. 1-4, in the infeed area of the table the type forms used in printing information directories are manually slid from the galleys so that they 50 are supported on the table top 10 and guided for lateral sliding movement by a guideway which is seen in Fig. 1 to include left and right side guides, numbered 15 and 16, respectively, which extend transversely of the table. The left side guide 15 is a bar having longitudinal slots 55 to receive mounting screws 17 on which the guide may be adjusted toward and away from the processing alley. The right side guide 16 is shorter and wider than the guide 15 and is transversely slotted to receive mounting screws 18 on which it may be adjusted toward and 60 away from guide 15.

A movable form aligning member 19 extends from the guide 16 to a position about even with the outer end of the guide 15. Member 19 is slidably mounted for movement toward and away from the guide 15 to dress 65 the type form in the infeed area between the guide 15 and the member 19, and is guided by laterally projecting pins 20 which are slidable in bushings 21.

Movement of member 19 is effected by a manual lever 22 which is pivoted on the table and operatively connected to member 19 by a link 23 (Fig. 4). The mechanism 70 19, 22, 23, preferably includes means (not illustrated) for retaining the member 19 in an advanced position toward the guide 15 in order to hold the type form upright.

In operation, a type form is manually placed about in 75 the position illustrated in Fig. 27, where the infeed pusher

engages one side of the form to feed the columns mechanically toward the processing alley; and is dressed by member 19.

The infeed pusher mechanism IV is supported on the table top 10 on a pair of spaced bridge frames 25 and 26 which span the infeed slideway to support a central, depending slide rail 27 on the slide flanges 28 of which a feed bar carrier 29 is slidably mounted for a feed stroke toward the processing alley, and a return stroke. An elongated pusher feed bar 30 is pivotally mounted beneath the carrier 29 transversely of the infeed slideway by upright ears 31 which flank carrier 29 and are impaled by the two ends of a pivot 32 on the carrier (Fig. 4); and a depending stop 33 on the carrier 29 overlaps feed bar 30 to hold it upright during a feed stroke.

To accommodate feed bar 30 to columns of various lengths it has a fixed bar piece 34 at one end and a movable bar piece 35 at the other end which contact the lower portions of the type in a column, and a central piece 36 which contacts the upper portion of the type and spans any gap left by adjustment of piece 35. Adjustment of piece 35 is provided by clamp screws 37 which extend through a slot 38 in bar 30.

The first form positioned in the infeed area I is pushed laterally to successively position the columns of that form in the processing alley, and as successive columns are pushed into and along the processing alley there is space in the infeed area to receive a second type form. A single feeding stroke of the pusher is thus broken into as many steps as there are columns in the type form. To permit the pusher to start feeding the next form, it must execute its return stroke, overriding the type form in a generally horizontal position and returning to upright feeding position when it clears the last column of the form.

Referring now particularly to Figs. 2 and 4, the return stroke is made possible by a laterally projecting guide pin 47 which extends from the left end of the feed bar 30 and traverses a lower run 48 of a guide track in guide bar 15 during a feed stroke. At the completion of a feed stroke, pin 47 engages a pivoted gate 49 and underrides the gate as shown by the full and broken line positions of Fig. 2, so that on the return stroke it may ride up the inclined surface of gate 49 to pivot the feed bar 30 to a generally horizontal position in which the pin traverses an upper run 50 of the guide track. At the end of the return stroke the pin 47 drops through an upright slot 51 to return feed bar 30 to upright feed position and place guide pin 47 again in the lower run 48.

Carrier 29 is reciprocated in the infeed slideway by two-way piston and cylinder device A, which is supported on the table top 10 across the processing alley from infeed area I. The device A includes a cylinder 42 secured to the table top and a reciprocable piston rod 43 which has its free end connected to carrier 29. Fluid is admitted to opposite ends of the cylinder 42 through conduits 44 and 45 under control of a four-way, two position solenoid valve V-1 (Figs. 1 and 40).

Control of the valve V-1 and operation of the piston and cylinder device A is explained in detail in describing the sequence of operations. Generally, it will suffice at this time to say that a feed stroke of the infeed pusher is initiated manually; and that the feed stroke is automatically interrupted each time a new column is pushed into the processing alley and automatically resumed whenever the infeed end of the processing alley is clear to permit movement of a succeeding column of type into the alley. The infeed pusher is returned to a starting position by manually actuating a switch when all the columns of the form have been fed into the processing alley.

Processing alley

Referring now particularly to Figs. 1 and 7, the proc-

essing alley II is open at the infeed end IIa (the right end as viewed in Fig. 1) to permit entry, extension, and retraction of a column pusher 67, and is open at the front side toward the infeed area I to receive columns from the infeed area. Across the alley from the infeed area a stationary guide bar 55 is secured to the table top 10 and extends longitudinally alongside the processing alley with a guide surface facing the infeed area.

Control switch means is provided adjacent the stationary guide bar 55 and responds to the position of columnar type in the processing alley to control infeed and to control the feed of the columns along the alley. The control switch means referred to includes a limit switch LS1 and a limit switch LS11, illustrated in Figs. 1, 1b, and 7.

The limit switch LS1 is supported on the table top 10 and is provided with a switch actuating plunger 56 (Fig. 1b) which is slidably mounted in a support 57 fixed on the table projecting through an opening in the stationary guide 55 and biased by a spring 56a to normally extend slightly into the processing alley. Movement of the plunger 56 by spring 56a is limited by a vertically disposed pin 56b carried by the plunger and engageable with guide member 55. The plunger is actuated by a column of type on movement of the type into the processing alley against the guide member 55.

The precise function of the switch LS1 will be detailed in describing the operation of the apparatus. Generally, the switch functions to stop the infeed pusher when a column of type engages the guide 55 and to initiate feed of the column along the processing alley. The switch LS1 is of a conventional type which is normally biased to an open position, is closed only so long as the plunger 56 is depressed by type, and returns to an open position when the column of type frees the plunger 56.

The limit switch LS11 is of a conventional type having two operative positions, and remains in either position to which it is moved until positively moved to the other position. As illustrated, the switch LS11 is actuated by two separate means. The first includes a pivoted actuating bell crank lever 59 which is biased to a non-actuating position by a spring 60. The bell crank lever 59 may be moved to a switch actuating position by means of a slideable plunger 61 which projects through an opening in the fixed guide member 55 in a manner similar to the plunger 56. Movement of the plunger 61 toward the processing alley is limited by a pin 61a (Figs. 1b and 7) carried by the plunger and engageable with guide 55. Accordingly, the plunger 61 is positioned to be engaged by a column of type on movement of the type into the processing alley to effect operation of the switch LS11. This function of the switch LS11 is utilized in conjunction with the switch LS1 to initiate feed of the type column along the processing alley.

The second actuating means for operating the switch LS11 is for the purpose of returning the switch to the normal position occupied before actuation by the plunger 61, and takes the form of a pivotally mounted switch actuating bell crank lever 62 having at one end a cam 60 engaging roller 63. At the end of the feed stroke of the column feed pusher 67 the roller 63 is engaged by a cam block 83 carried by the column pusher to pivot lever 62 clockwise and return switch LS11 to normal position. As will be explained in greater detail hereinafter, this function of the limit switch LS11 is utilized to prevent infeed movement of the type from the infeed area until the infeed end of the processing alley is completely clear of type.

The alley feed mechanism, generally designated V, acts through piston device B (Figs. 1 and 40), having a cylinder 65 and piston rod 66 beneath the table top 10, to push successive columns of type along the processing alley as illustrated in the sequence views Figs. 27 to 30. The free end of the piston rod 65 is connected beneath

the table 10 to a column pusher 67 (Fig. 5) which has a rod receiving block beneath the table, the upper end 68a of which extends into a longitudinal slot 71 in the table top and is surmounted by a pusher plate 69 (Fig. 7) which rides on top of the table and has a reduced, depending attaching neck 69a secured to the upper end 68a of the block, by screws 70; so that pusher 67 is slidably guided on the table for reciprocation along the processing alley. As best seen in Fig. 7, the pusher plate 69 has a longitudinal clearance groove 69b facing guide member 55 to receive switch actuating plungers 56 and 61.

The individual lines of type which comprise the type column stand upright on edge on the table top 10, normal to the plane of the table, as illustrated in Fig. 5; to keep the type from tipping over backward when pusher 67 is withdrawn, the table top is inclined downwardly (toward the left, as viewed in Figs. 1, 1a, and 5) so the lines of type lean slightly forward (to the left in Fig. 5).

The inclination of the table tends to cause the lines of type in the processing alley to fall forward as a column is pushed along the alley; and to avoid this, the forward end of the pusher plate 69 carries a leaf spring member 72 which pushes only on the lower portion of the last line in the column to push the column along the processing alley. The spring member 72 has a flat upper portion 72a which is secured to the pusher plate 69 by means of screws 73 and includes a lower portion 72b which is curved forwardly and then slightly rearwardly, as best seen in Fig. 5; and thus provides a resiliently movable pusher to push the last line of type in the column only at its lower portion.

When the leading column of type is pushed from the infeed end of the processing alley into the vicinity of the revising area, as illustrated in Fig. 29 for example, the spacer 11 between the first column of type and the second column of type is left exposed and may easily fall into the processing alley. This is prevented by a spring biased pivoted latch finger 75 which is seen in Fig. 6 to be pivotally mounted on an upright pin 76 near the right hand end of the processing alley, and which is normally biased by a leaf spring member 77 to the full line position illustrated in Fig. 6 wherein an angularly bent end portion 75a engages over the end of the spacer 11 to hold the spacer in position when the preceding column of type is moved away. As illustrated by the broken line showing in Fig. 6, leaf spring 77 is yieldable to permit latch finger 75 to pivot clockwise so the spacer 11 may be slid endwise out of the processing alley (see broken line position in Fig. 6) to free the succeeding column for movement into the alley.

Means is provided on the alley feed pusher 67 to withdraw the spacer 11 on the return stroke of the pusher. As best seen in Figs. 6 and 7, such means comprises a pivoted hook-like member 79 having at one end a hook portion 79a which engages the forward end of the spacer 11, and on the return stroke of the pusher, withdraws the spacer to the broken line position of Fig. 6. The hook member 79 is pivoted by means of a pivot pin 80 supported on the pusher plate 69, and a leaf spring 81 normally biases the hook member toward an operative spacer engaging position. The nose of the hook member 79 is formed with an inclined end surface 81 which engages the nose of the latch finger 75 on forward movement of the pusher 67 to force the hook member to ride over the spacer. The operative position of the hook member 79 to properly position the hook portion 79a may be adjusted by an adjustment screw 82 threadably mounted on the plate 69.

As previously explained, return operation of the limit switch LS11 (Fig. 1b) is obtained at the end of the feed stroke of the alley pusher through the medium of a switch actuating bell crank 62 carrying a roller 63. This actuation of the switch LS11 is obtained by means of a cam block 83 secured by screws 84 to the top of the

pusher plate 69. A side surface 85 (Fig. 7) on the cam block 83 engages the roller 63 at the end of the feed stroke of the alley pusher to operate the switch LS11, thus indicating to the electric circuit that type has been removed from the infeed area of the processing alley to leave the infeed end clear to receive a succeeding column of type from the infeed area.

As best seen in the fluid circuit diagram of Fig. 40, fluid is admitted to opposite ends of the alley pusher cylinder 65 through conduits 86 and 87 under control of a solenoid operated, four-way, two position valve V2. Control of the valve V2 and operation of the piston and cylinder device B will be described in detail hereinafter. In general, movement of the pusher in a feed direction is initiated automatically when there is type in the infeed end of the processing alley within the range of the pusher stroke, and when any type in the revising area of the processing area is released by the clamping means. Once initiated, movement of the alley pusher may continue through a complete feed stroke or through only a partial feed stroke, depending upon the amount of type in the alley ahead of the pusher, and in either case through a return stroke to the starting position.

If the amount of type in the processing alley ahead of the pusher will permit the pusher to move through a complete feed stroke, at the end of such a stroke a limit switch LS2 (Fig. 1) is actuated by means carried on the pusher to stop the feed movement and to reverse the pusher. The switch LS2 is mounted beneath the table 10, and is actuated by the head of a screw 89 (Fig. 5) adjustably mounted in the forward end of the pusher block 68. As will be described in detail presently, actuation of the switch LS2 is effective to reverse the stroke of the pusher.

If the amount of type in the processing alley ahead of the pusher will not permit a complete stroke of the pusher, the type at the head of the column in the processing alley at the outfeed end will cause actuation of a limit switch LS6 (Fig. 1) to stop the pusher short of a complete stroke and to initiate return of the pusher to the starting position. The limit switch LS6 and its operation will be described in more detail presently.

After either a complete feed stroke of the alley pusher or a partial stroke of the pusher, its movement is reversed and the pusher returns to the starting position. At the end of the return stroke an arm 90 on the pusher works through a screw 91 to actuate a limit switch LS12 (Fig. 1), mounted beneath the table 10. LS12 functions as a safety switch to prevent operation of the infeed pusher unless the alley feed pusher is at rest in the withdrawn position.

Clamping

In the revising area IIc, the processing alley is flanked by elongated clamping members. A column of type is pushed between the clamping members by the column pusher and is pushed out of the revising area into the outfeed end of the processing alley by succeeding columns as the latter are pushed along the alley into the revising area.

Referring to Figs. 8, 9, 14 and 15, the clamping members include at one side of the alley an elongated clamping anvil 95 which is actuated by the solenoid operated cam mechanism C1, and at the other side of the alley an elongated clamping bar 96 which is operated by the piston and cylinder actuated toggle mechanism C.

The clamping anvil 95 is a flat plate-like member having one side surfaced with a strip of rubber 97 (Figs. 9 and 15) to engage the retainable lines of type in the column of type in the revising area. The anvil is slidable on the table top 10 toward and away from the processing alley.

The anvil 95 is biased in a type releasing direction by means best illustrated in Figs. 14 and 15, including a spring 97 positioned in a pocket in the anvil and bearing

at one end against an adjustable plug 98 also positioned in the anvil. At the opposite end, the spring 97 bears against a slideable plunger 99 having one end positioned against the head of a screw 100 fixed in the table 10, and projecting upwardly into a recess 101 in the anvil 95.

At the side of the anvil 95 opposite its type engaging side is a pair of longitudinally spaced cam surfaces 102 and 103 (Fig. 8), which are inclined relative to the length of the anvil. A longitudinally reciprocal cam bar 104 is positioned alongside the anvil and has longitudinally spaced cam surfaces 104a and 104b engaging respectively, with the surfaces 102 and 103 on the anvil. The cam bar is backed against a guide member 104c and slides along the member 104c. The solenoid means C1 for reciprocating the cam bar is best seen in Fig. 13 to include a fixed upright 105 having its opposite ends connected respectively to the cores 106 and 107 of solenoids S16 and S17, which are omitted from Fig. 1. The cores 106 and 107 of the solenoids are T-shaped bars which are slidably mounted respectively in guides 108 and 109 (Fig. 8) provided on the table 10. The solenoid S16 is energized to move the cam bar 104 toward the right as viewed in Figs. 8 and 13 to effect movement of the clamping anvil in a type gripping direction. The solenoid S17 is energized to move the cam bar in a type releasing direction.

The controls for regulating energization of the solenoids S16 and S17 will be described in detail hereinafter. Generally, the clamping solenoid S16 is energized to clamp retainable lines of type when type is positioned in the revising area of the processing alley. The solenoid may be energized either on actuation of the limit switch LS2 at the end of a complete feed stroke of the alley feed pusher or on actuation of the limit switch LS6 when the processing alley is filled with type. The solenoid S17 is energized to release the type after the stripping operation has been completed.

As best seen in Figs. 8 and 9, the elongated clamping bar 96 which opposes the clamping anvil 95 comprises a flat plate-like member slidably mounted on the table top 10 and surfaced at the type engaging face with a strip of resilient rubber-like material 110 which may tightly grip the retainable lines of type without injuring them. The clamping bar 96 is guided for slideable movement on the table 10 toward and away from the processing alley by guide members 111 and 112 (Fig. 8).

Movement of the clamping bar 96 toward and away from the processing alley is obtained by a toggle mechanism including an upwardly and downwardly movable carrier 116 which forms the knee of the toggle. One link or leg of the toggle is formed by parallel links 113 and 114 each having one end pivoted to the carrier 116 and their opposite ends pivotally connected to the clamping bar. The other link or leg of the toggle is formed by parallel links 117 and 118 each having one end pivoted on the carrier 116 and their opposite ends pivotally connected to a mounting block 120 adjustably fixed on the table top 10, as by screws 121.

Parallel links 113 and 114 are connected to clamping bar 96 through a block 124 to which the links are pivoted. The block 124 is secured to an overlying connector plate 125 by a screw 126, and the plate 125 is in turn adjustably attached to the clamping bar by screws 127 which pass through elongated slots in the plate and connect with the clamping bar.

Movement of the clamping bar in a type gripping direction is limited by engagement of the bar with type in the revising area of the processing alley. Movement of the clamping bar in a type releasing direction is limited by a stop device 122 having a stop screw 123 engageable by block 124.

The range of movement of clamping plate 96 may be adjusted by adjustment of the slide block 120 which abuts an adjustment screw 129 in a block 130 secured to the table top 10.

The toggle described is actuated by the piston and cylinder device C seen in Fig. 9, which includes a cylinder 132 having its lower end pivotally mounted at 133 on a carrier 134 supported by rods 135 depending from the table 10. A piston reciprocal in the cylinder 132 is provided with an outwardly extending piston rod 136 which is suitably connected to the carrier 116 which forms the knee of the toggle linkage.

Fluid is admitted to opposite ends of the cylinder 132 to make and break the toggle linkage to operate the clamping bar 96 by means of conduits 137 and 138 (Fig. 40) under control of a solenoid operated, four way, two position valve V3, as will be explained in detail with the operation of the apparatus. In general, operation 15 of the piston and cylinder device C to obtain movement of the clamping bar 96 in a type gripping direction is initiated at the same time that energization of the clamping solenoid S16 occurs, that is, under control of the limit switch LS2 or the limit switch LS6. Operation of the piston and cylinder device to move clamping bar 96 in a type releasing direction is initiated at the same time that energization of the type releasing solenoid S17 is initiated, that is, upon return of the stripping device for lifting removable lines of type to a rest position.

As illustrated in the fluid circuit diagram of Fig. 40, the valve V3 for controlling operation of the piston and cylinder device C is operated by solenoids S5 and S6. The solenoid S6 is energized to obtain movement of the clamping bar 96 in a clamping direction, and the solenoid S5 is energized to obtain movement of the clamping bar 96 in a type releasing direction.

In operation, the clamping solenoid S6 for bar 96 is energized simultaneously with the clamping solenoid S16 for clamping anvil 95. However, since the solenoid S16 35 for the clamping anvil 95 directly actuates the clamping bar 104, while the solenoid S6 moves the clamping bar through the medium of a valve and a piston and cylinder device, the clamping anvil 95 necessarily moves into position against the retainable lines of type at one side 40 of the column before the clamping bar 96 engages the other side of the column. Thus, the anvil functions as a movable stop which is normally withdrawn from the edge of the column of type to permit free movement of the column in and out of clamping position; but which moves against the type to fix a definite position for one 45 side of the column and retain that position against the action of the clamping bar so as to positively locate the type column in the revising area.

Movement of the piston rod 136 to operate the clamping bar 96 also controls other operations of the apparatus. Accordingly, as best illustrated in Figs. 1 and 12, limit switches LS3 and LS5 are supported on the table top 10 alongside the path of movement of the carrier 116 which forms the knee of the toggle linkage for actuating the clamping bar 96. When the piston rod 136 is at the upper extreme of its movement, retracting the clamping bar 96 (broken line showing of Fig. 12), neither of the limit switches LS3 or LS5 is actuated.

On movement of the piston rod 136 and the carrier 60 116 downwardly to move the bar 96 in a clamping direction, a cam member 140 on the carrier 116 engages the switch arm of switch LS3 to actuate the latter and thereby initiate movement of the stripping device for lifting out the removable lines of type from the column 65 in the revising area. The limit switch LS5 is arranged to be actuated momentarily by a cam member 141 on the carrier 116 during upward movement of the carrier; and this may either initiate infeed of a column of type from the infeed area to the processing alley, or feed of a column of type along the processing alley from the infeed end to the processing area, depending upon the 70 position of the limit switch LS11 previously referred to.

Stripping

75 As previously described, at least some, and possibly

all of the columns of type positioned in the infeed area of the apparatus include some removable lines of type interspersed with the retainable lines of type which comprise the major portion of each column. In order to obtain clamping of the retainable lines of type in the revising area of the processing alley and to permit removal of the removable lines of type, the removable and retainable lines are differently formed, as best illustrated in Figs. 9, 15 and 16. As seen in Figs. 9 and 15, the retainable lines of type RT are rectangular slugs of a predetermined length and height. The removable lines of type RM are each irregularly formed at the ends to provide a lower portion RM1 of shorter length than the retainable lines of type, an intermediate portion RM2 of the same length as the retainable lines, and an upper portion RM3 which is longer than the retainable lines of type to provide near the top of the removable lines at opposite ends outwardly extending lifting lugs, so that a pair of vertically reciprocable lifting, or stripping rails 145 and 146 which flank the column above the clamping members and beneath the lugs may lift the removable lines above the retainable lines. In the machine illustrated, the stripped removable lines are gathered from the stripper manually.

The lower portion RM1 of the removable line provides relief areas at opposite ends of the slug so that when the column of type is clamped in the revising area by clamping bars 95 and 96 which exert clamping pressure on the ends of the retainable lines, the removable lines are not clamped but are left free to be lifted by the stripping rails.

Opposite end faces of the intermediate portion RM2 of the removable line provide positioning surfaces, and when the removable slugs are set in a column with retainable slugs the positioning surfaces are coplanar with the ends of the retainable slugs, and in the type form are engaged by spacers 11 which retain the removable slugs against longitudinal shifting (laterally of the column) with respect to the retainable slugs.

The removable lines of type, or slugs, and type forms including such slugs, are disclosed and claimed in our copending application, Serial No. 664,579, filed June 10, 1957.

When the type column is moved into the revising area of the processing alley, the stripping rails 145 and 146 are in the retracted, broken line positions of Fig. 9 so as to be overridden by the lifting lugs as a column of type slides along the processing alley. The raised position of the stripping rails 145 and 146 is illustrated in full lines in Figs. 9 and 11, and in broken lines in Fig. 15.

Reciprocal movement of the stripping rails 145 and 146 is afforded by the piston and cylinder device D which includes a cylinder 153 suitably supported on and depending from beneath the table top 10 and a piston rod 154 having its free end connected centrally to an actuating plate 151. The plate is in turn connected to the lower ends of four vertically reciprocal rods 147, 148, 149, and 150, 147 and 148 having their upper ends connected to lifting rail 145 and 149 and 150 having their upper ends connected to rail 146.

The rods 147 and 148 for lift rail 145 project through elongated slots 156 (Fig. 8) in the clamping bar 96 to permit movement of the clamping bar toward and away from the type column in the revising area. The rods 149 and 150 for lift rail 146 pass through comparable slots 157 in the clamping anvil 95 to permit movement of the anvil toward and away from the type column in the revising area.

The lift rail 145 is secured to lift rods 147 and 148 through the medium of an elongated stiffener plate 158 (Figs. 8 and 9) which overlie the lift rail. The stiffener plate is suitably secured near opposite ends to the top of the lift rods 147 and 148, and the lift rail 145 is secured adjustably to the stiffener plate 158 by means of screws 159 which are threaded into the lift rail and which

pass through elongated slots 160 provided in the stiffener plate to permit adjustment of the lift rail relative to the stiffener plate. The lift rail 145 is not attached directly to the lift rods 147 and 148, but includes elongated transversely extending slots 161 which embrace the lift rods 147 and 148 to permit adjustment of the rail relative to the lift rods when the rail is adjusted relative to the stiffener plate.

The lift rail 146 is attached to lift rods 149 and 150 in a somewhat similar fashion, although the lift rail 146 is not slotted for adjustment. As seen in Figs. 8 and 9, rail 146 is secured to an overlying, elongated stiffener plate 163 by means such as screws 164, and the stiffener plate 164 is in turn suitably secured to the upper ends of rods 149 and 150. Rail 146 is provided with suitable openings through which pass the lift rods 149 and 150.

Means is provided to limit the downward movement of the lift mechanism in order that the lift rails 145 and 146 will be slightly spaced above the slideable clamp plates 95 and 96 to permit movement of the latter freely when the lift rails are in the lowermost positions. The movement limiting means referred to includes a pair of stop devices 166 associated with rail 145. As best seen in the sectional view of Fig. 10, each of the stop devices 166 includes a stop screw 167 which is adjustable threadably in the stiffener plate 158 and carries a locknut 168 provided for retaining the screw 167 in adjusted positions. As seen in Fig. 10, the stop screw extends through an elongated slot 169 in the lift rail 145 to permit adjustment of the rail relative to the stiffener plate 158. The stop screw also projects at its lower end into an elongated slot 170 provided in the reciprocal clamping plate 96 to permit movement of the clamping plate 96 for gripping type in the revising area. At the lower end, the stop screw 167 bears on the top of the table 10 to thereby limit downward movement of the lifting mechanism.

As best illustrated in the hydraulic diagram of Fig. 40, fluid is admitted to opposite ends of the stripper cylinder 153 through conduits 172 and 173 under control of a solenoid operated, four way, two position valve V4. Control of the valve V4 and operation of the piston and cylinder D will be described in detail with the operation of the machine.

In general, fluid is admitted to the stripper cylinder to initiate elevation of the strippers when the limit switch LS3 is actuated by movement of toggle carrier 116 to clamp the column. Return of the strippers to retracted position is manually initiated by pressing a pair of "Down" pushbutton switches D2 and D3 on a control panel 175 which is supported on top of table 10, as illustrated in Fig. 1. Manual control of the return movement of the strippers by two pushbuttons makes it substantially impossible for an operator to have a hand injured by the stripper rails, because he must have both hands clear of the rails to initiate stripper return.

According to the invention, in order to obtain automatic operation of the apparatus, reciprocation of the strippers serves to operate other controls. As best illustrated in Figs. 1 and 11, limit switches LS4 and LS15 are arranged on the table top 10 alongside the lift rods 148 and 150, respectively.

The switch LS4 is actuated momentarily near the end 65 of the return stroke of the strippers by means of a switch actuating rod 177 (Fig. 11) which is adjustably supported on a plate 178 secured to the stiffener plate 158 by means of screws 179. Limit switch LS15 is actuated at the end of the return stroke by a switch actuating screw 180 adjustably supported on an arm 181 which is secured to the stiffener plate 163 by screws 182.

As explained more in detail in describing the operation of the apparatus, actuation of the limit switch LS4 momentarily near the end of the downward stroke of the 75 lifting apparatus serves to initiate type releasing move-

ment of the clamping anvil 95 and the clamping bar 96. The limit switch LS15 is a safety switch which prevents operation of the alley feed pushing mechanism unless the lift mechanism is in the down position, to avoid possible interference between the strippers and the lift lugs RM3 in a column of type entering the revising area.

Outfeed

Columnar type is pushed longitudinally along the processing alley from the revising area to the outfeed end of the alley by the succeeding columns of type in the processing alley, as seen in Figs. 32 and 34. The head of the column of type moving from the revising area to the outfeed end of the processing alley is held upright by a spring biased follower plate 190 (Figs. 19 and 20) having a lower reduced end portion 191 which is reciprocable in an elongated slot 192 formed in the table top 10. The lower end portion of the follower is flanged as seen at 193 in Figs. 19 and 20, and the flanged portion 193 is secured by screws 194 to a plate 195 which is slidable beneath the table 10 in guides 196.

The follower is biased from the outfeed end of the processing alley toward the revising area of the alley by means of a clock type spring 198 and is movable against the bias of the spring toward the outfeed end of the processing alley by the column of type moving along the alley. One end of the spring 198 is secured beneath the follower plate 195 by screws 199. The spring extends longitudinally beneath the table along the slot 192, and the opposite end of the spring is wound in a coil on a fixed spool 200 (Fig. 18). The spool is supported on a shaft 201 which is rotatably mounted beneath the table 10 but which is normally held against rotation by means of a one way ratchet 202 secured to the spool and engaged by a pivotally mounted pawl 203, as best illustrated in Fig. 18. The pawl 203 is in the shape of a bell crank lever pivoted at 204 and biased into engagement with the ratchet 202 by means of a curved leaf spring 205 secured beneath the table 10.

In operation, it will be appreciated that as the follower 190 is moved by type toward the right as viewed in Figs. 18 and 20, the clock spring 198 will be more tightly coiled on the fixed spool 200 to bias the follower against the lead line of type in the column. When the column of type is pushed laterally from the outfeed end of the processing alley into the composing area 3, as illustrated in Fig. 35, the spring 198 rewinds itself on the spool to draw the follower back in the processing alley against the lead line of type therein.

The pawl and ratchet mechanism 202, 203 is provided for adjusting the tension of the spring 198. It will be seen that if the spool is adjusted counter-clockwise as viewed in Fig. 18, the spring 198 will be more tightly wound on the spool to thereby increase the tension on the follower 190. Conversely, if the pawl 203 is held out of engagement with the ratchet 202, the spool 200 may be rotated clockwise to decrease the tension on the follower 190.

As previously described, the table 10 which supports the composing apparatus is inclined downwardly toward the left as viewed in Fig. 1. The principal function of the follower 190 is to engage the lead line of type in the processing alley to prevent such line of type and succeeding lines of type from tipping forwardly to fall over and collapse the column. When the first column of type is fed from the infeed end of the processing alley to the revising area of the processing alley, as shown in Figs. 29 and 30, the lead line of type in the column does not reach the follower 190, so a suitable temporary filler block 206 is inserted manually between the follower and the head of the column to retain the column in upright position. When the column has been fed sufficiently along the processing alley, to a position such as that illustrated in Fig. 32, the filler block may be removed; and thereafter,

the exposed head of the columnar type in the processing alley may always reach the follower 190.

As explained more in detail in describing the operation of the apparatus, the head of the type column in the processing alley eventually is moved to the end of the alley, as illustrated in Fig. 34, and abuts against a stop and guide member 208 (Figs. 20 and 34) which extends across the end of the processing alley, forms the end of the alley, and provides a guide surface to guide the movement of a new column length as the latter is pushed laterally from the outfeed end of the processing alley into the composing area III. As the head of the column in the processing alley reaches the end of the alley and engages the guide member 208, the follower 190 at the head of the column moves into a recess 209 in the guide member 208 to be out of the path of a pusher which severs the new column length.

Movement of the follower 190 into the recess 209 is utilized to actuate a limit switch LS6 supported beneath the table 10, as seen in Figs. 1 and 20. As best seen in Fig. 20, the switch LS6 is actuated by an adjustable switch-actuating screw 210 which is threaded into a bracket 211 secured by screws 212 to the under surface of the follower plate 195. A lock nut 213 is provided for holding the screw 210 in adjusted positions.

Actuation of the limit switch LS6 in the manner described is utilized, as explained in detail later, to stop the feed movement of the alley feed pusher when the column reaches the end of the alley. Actuation of the switch LS6 also is utilized to initiate a sensing operation to detect the separation of multiple line listings when the new column length is severed, as described presently. Additionally, actuation of the switch LS6 also serves to initiate movement of the clamping anvil 95 and the clamping bar 96 to gripping positions. Further, the switch LS6 also initiates operation of the outfeed severing pusher to sever a new column length and push the same into the composing area III. The last two operations are effected through a time delay means which permits operation of the multiple line listing sensing apparatus, so that the sensing device may check for multiple line listings before severing the new column length. In the event a multiple line listing is sensed, the apparatus is stopped before the severing occurs to permit manual correction, as explained in detail presently. In the event that no multiple line listing occurs, clamping and severing follow actuation of the limit switch LS6.

Multiple line listings in a telephone directory are those wherein, for one reason or another, the information concerning the subscriber cannot all be included in a single line. In such listings, the first line of the listing begins at the margin of the column in line with the majority of the remaining lines in the column, while the second and following lines are indented; and all lines of a multiple line listing should be in the same column. Accordingly, the sensing mechanism, generally designated VIII, is provided to inform an attendant or operator when separation of a multiple line listing will occur in the operation of severing a new column length, so the operator may correct it.

In the apparatus as illustrated, the heads of the columns of type are at the left as illustrated in Figs. 27 to 38 so that the type in each column which will print the left-hand margin of the directories is at the right as it moves through the processing alley, next to the clamping anvil. Accordingly, the second line of type in a multiple line listing is indented from the righthand margin of the line; and, the sensing apparatus is therefore adapted to feel the presence or absence of a type character at the righthand margin of the first line of type following the column to be severed, and thus determine when the separation of a multiple line listing will occur.

As best illustrated in Figs. 8, 17, and 19, the sensing mechanism includes a pivoted sensing lever 220 having at one end a rigid, depending stop finger 221 which overlies

the righthand printing character of the normal lines of type in the alley. Lever 220 is pivoted on a bracket 222 on the table top by means of a pivot pin 225 which is mounted in a pair of upright spaced ears 224 on the bracket. As viewed in Fig. 20, the left end of the pivoted lever 220 is normally pulled down by a tension spring 226 to hold finger 221 clear of the type.

As noted previously, the sensing operation occurs on actuation of the limit switch LS6 when the column of type abuts against the guide member 208. Actuation of the limit switch LS6 momentarily energizes a push type solenoid S13 (Fig. 19) which is supported beneath the table 10. The core 228 of solenoid S13 is slidable in guides 229 and connects with a plunger 230 which extends through the table top 10 beneath the left end of lever 220 to elevate that end when the solenoid is energized and thereby lower finger 221 onto the top of the line of type. If the line is a normal one having a type character at the right-hand margin the finger 221 strikes the character to stop the lever, and the spring 226 returns the lever to normal position.

If the line sensed by the finger is the second or following line of a multiple line listing, it will have an indented righthand margin, as illustrated at 232 in Fig. 19, into which finger 221 moves. In this case, the left end of the sensing lever 220 rises until an actuating abutment 233 on the lever engages the switch arm of a conventional two position limit switch LS7 (Fig. 19) to open the switch. This disables the machine and lights a pilot light PL2 adjacent switch LS7 to inform the operator of the multiple line listing.

The operator may restart the machine by manually depressing the left hand end of the feeler lever 220 and depressing a reset button 235 to reset the switch LS7; whereupon type in the revising area is clamped and stripped, and the new column length in the outfeed end of the processing alley is severed. It will be recalled that the stripping rails remain elevated until the operator presses the two "Down" buttons; so the machine is again stopped and the operator manually may remove from the severed column length and replace at the head of the column in the processing alley any severed lines which are part of the multiple line listing.

Severing

A new column length of a predetermined number of lines, which as illustrated is shorter than the length of the columns in the form originally positioned in the in-feed area, is severed from the head of the column in the processing alley by pushing such column length laterally from the processing alley into the composing area III, as best illustrated in Figs. 35 and 36. The severing mechanism, generally designated IX in Fig. 1, includes a rectangular outfeed pusher frame 240 which slides in guides 241 and 242 laterally across the processing alley toward and away from the composing area III. The pusher frame includes parallel longitudinally extending side pieces 243 and 244 connected by parallel cross bars 245 and 246. The cross bar 245 acts as a severing bar which engages the side of the column in the processing alley to push the new column length laterally. Both of the cross pieces 245 and 246 may, if desired, consist of separate overlapping lengths of material to permit adjustment of the width of the pusher in order to sever columns of varied lengths.

A slideway for the new column length is provided by the guide member 208 (previously referred to) on the left side as viewed in Fig. 1, and on the right side by a spring biased guide bar 248 which functions as a stripper to permit movement of the desired column length laterally from the processing alley and to retain the succeeding line of type in the processing alley. As seen in Figs. 8 and 17, the stripper bar 248 includes a pair of laterally projecting rods 249 which are slidable in a bushing 250 supported on the table 10. Springs 251 embrace the rods 249 and urge the stripping bar 248 outwardly toward the revising

area III. The bar 248 has a beveled leading end 252 to guide the severed column length properly into the composing area III.

The stroke of the column severing pusher 240 is sufficiently long to move the severed column of type completely from the processing alley, past the stripping bar 248, and into the composing area as illustrated in Fig. 35. As soon as the severed column clears the processing alley, the limit switch LS6 (Fig. 20) is released to return to its normal position by permitting the follower return spring 198 to move the follower 190 into an elongated recess 255 (Figs. 1 and 20) in the outer face of the longitudinal frame member 243. Return of switch LS6 to its normally open position permits the return stroke of the 15 pusher, as will appear presently.

During the fed stroke and on the return stroke of the pusher 240, the outer face of the longitudinal frame member 244 slides along the lead line of type in the processing alley to prevent this line from tipping forward.

20 On the return stroke of the pusher 240, when the cross piece 245 clears the follower 190, the follower is returned to the head of the column in the processing alley by the spring 198. As seen in Figs. 1, 8 and 18, the slot 192 in the table 10 along which the follower 190 moves is offset toward the composing area III, which permits the follower to clear the pusher and return to the head of the column in the processing alley by the time the cross piece 245 reaches a rest position releasing the head of the column in the processing alley. Thus, the pusher 240 and 25 the follower cooperate to prevent the lead line of type in the processing alley from tipping forward.

The pusher 240 is operated by the piston and cylinder device E, which includes a cylinder 260 (Figs. 1 and 40) secured to the table top 10 and a reciprocable piston rod 35 261 suitably connected to the cross piece 245 of the pusher. Fluid is admitted to opposite ends of the cylinder 260 to obtain operation of the pusher through the medium of conduits 261 and 262 (Fig. 40), under control of a solenoid operated, four-way, two-position, valve 40 V5.

Operation of the piston and cylinder device E for the feed or pushing stroke of the pusher 240 is initiated, as previously described, on operation of the limit switch LS6 when the lead line of type in the processing alley engages the guide 208. Return operation of the pusher is initiated 45 by a limit switch LS8 (Fig. 1) supported on the table top 10 within the bounds of the pusher frame 240, and actuated by means of an adjustable screw 264 carried by the rear cross piece 246 of the pusher frame.

The operating movements of the pusher 240 are utilized to control other operations in the apparatus through limit switches LS9 and LS14 which are supported on the table top 10 as illustrated in Fig. 1. The limit switch LS9 is actuated by a rod 265 projecting from the end of the cross piece 246. The arrangement of the switch and the actuator 265 are such that the switch LS9 momentarily closes just before the return stroke of the pusher 240 is completed to initiate the feed of a column spacer between the newly severed column length and the processing alley. The limit switch LS14 is actuated by the right forward corner of the pusher frame 240, as seen in Fig. 1, when the pusher frame is at rest at the end of the return stroke. The switch LS14 functions as a safety switch to prevent descent of the stripper to rest position until the severing pusher is completely retracted. This is necessary since downward movement of the stripper may cause feed of the columnar type in the processing alley, and this must not occur until the pusher 240 is completely retracted.

Spacer Feed

As the newly severed columns of predetermined lengths are moved laterally into the composing area III, column spacers are successively inserted between the processing alley and the adjacent column in the composing area; and 75 for this purpose a column spacer magazine and space

guideway occupy the area of table 10 alongside the operating mechanism for clamping anvil 95. The sides of the magazine are defined by a pair of parallel guide members 270 and 271 (Fig. 1) which are adjustably spaced to serve as end guides for spacers of various lengths. The spacers in the magazine are urged by a follower bar 272 toward an end of the magazine which is defined by the outer face of the bar 104c which functions as a backup member for the reciprocable cam bar 104 for actuating the clamping anvil 95. The outer face of bar 104c acts as a stop to limit forward movement of the spacers, and also cooperates with an extension 270a on guide member 270 to define a guideway through which the spacers slide endwise into the composing area.

Follower bar 272 is provided with a rearwardly projecting guide rod 273 slidably supported in a bushing 274 and with rearwardly projecting parallel bars 275 and 276 which have biasing cables 277 and 278, respectively, attached to their under surfaces and extending forwardly in grooves 279 and 280 in the table top 10 to pass through slots 281 and 282 to the underside of the table. As best seen in Fig. 21, the cables then pass around pulleys, such as pulley 283, and have their ends secured to a weight 284 which hangs beneath the table 10 to bias the follower 272 and spacers toward the guide member 104a.

The spacer feed mechanism, generally designated in Fig. 1, includes a long, narrow spacer feed blade 290 (Fig. 23) which extends upwardly through an elongated slot 291 (Figs. 1, 8 and 22) in the table top and longitudinally along the table parallel to the guide member 104c. The lower portion of the spacer feed blade 290 is enlarged, as best seen in Fig. 23, to provide a plate-like carrier portion 292 which is slidably in guides 293 secured beneath the table 10. A bracket 294 attached adjacent the right end of the spacer feed blade 290, as viewed in Fig. 21, connects the blade to the actuating piston and cylinder device F (Fig. 1).

The piston and cylinder device F includes a cylinder 295 secured to the underside of the table, and a reciprocable piston rod 296 extending from the cylinder and connected to the bracket 294 as best seen in Fig. 21.

As best seen in Fig. 22, the follower 272 urges the column spacers 297 forwardly on the table 10 to abut a first spacer against the guide member 104a, with a portion of the spacer overlying a portion of the elongated slot 291. On movement of the spacer feed blade 290 to the left as viewed in Figs. 21 and 22, the end of the blade abuts the end of the first spacer, and pushes the spacer endwise along the spacer guideway defined by guide member 104c and extension 270a of the guide member 270. The stroke of the spacer feed blade 290 is sufficient to move the column spacer into the composing area to the position illustrated in Fig. 36, where a spring finger 299 on the end of guide member 104a prevents it from falling toward the processing alley. The spring finger 299 retains the spacer in place, but may yield on movement of a succeeding column length into the composing area to permit the column length to pass the spring finger.

Fluid is admitted to opposite ends of the spacer feed cylinder 295 by means of conduits 301 and 302 (Fig. 40) under control of a solenoid operated, fourway, two position valve V6. Operation of the piston and cylinder device F to move the spacer feed blade through a feed stroke is initiated, as previously described, by the momentary actuation of the limit switch LS9 on return movement of the column severing pusher. Movement of the spacer feed blade through a return stroke is initiated by operation of a limit switch LS10 (Figs. 1 and 21) supported beneath the table and positioned to be actuated at the end of the feed stroke of the spacer feed blade by a switch actuating pin 303 supported on a bracket 304 (Fig. 1) extending laterally to the rear from the spacer feed plate 292.

Composing area

Generally, as seen in Figs. 1 and 26, the composing

75

area III is a rectangular space 306 in the table top 10, which is recessed to receive a type holding galley, illustrated in broken lines at 307 in Fig. 1, onto which the newly severed column length is pushed; and on which a newly composed page form may be made-up by conventional means. If desired, the galley 307 may include parallel spring-like guide members 313 and 314 for holding the new type form as it is composed.

The first column of the new type form is pushed into the composing area directly by the severing pusher 240, as illustrated in Fig. 35. As successive columns of type are pushed toward the composing area by the pusher 240, as illustrated in Fig. 38, the preceding columns of type are pushed by the succeeding columns of type laterally toward the rear of the apparatus until the galley 307 has been filled. As illustrated, the galley holds four columns of type, although it may hold three or five or other numbers of columns.

To indicate when a galley is full and should be replaced by an empty galley, a limit switch LS13, illustrated in Figs. 1, 24, 25 and 26, having a projecting spring-loaded actuating plunger 316 is supported in a housing, generally designated 315, which is supported on the table top 10 alongside the composing area III. The switch is operated by a cam member 317 which is secured by a set screw 318 on a cam shaft 319 which is rotatable in the switch housing 315 and projects out of the housing where it has a second cam 320 in the path of the columns of type moving into the galley 307. The cam 320 is normally positioned as illustrated in Fig. 25 and movement of a fourth column of type into the galley pushes the first column against cam 320 to rotate cam shaft 319 clockwise as viewed in Fig. 25 and depress switch plunger 316 to actuate switch LS13. The cam 317 is cylindrical, but has a flat portion 321 which permits the plunger 316 to assume its normal position; and clockwise rotation of the cam member moves the cylindrical surface of the cam 317 into actuating engagement with the plunger.

Actuation of the limit switch LS13 serves to disable the apparatus and light a pilot light PL3 on top of the housing 315, to inform the operator that the new form is completed and the full galley should be removed.

After the filled tray is removed and replaced by an empty tray, operation of the machine is again initiated by manually rotating cam 320 counterclockwise to its normal position, thus resetting switch LS13, and then pressing the "Down" button.

At the extreme left end of the table 10, there may be provided, if desired, a means generally designated 321 for storing and feeding multiple column headings for insertion at the head of columns in the new form in the composing area III.

Fluid circuit

The various fluid operable piston and cylinder devices A-F are preferably operated by means of air under pressure, which may be supplied by any suitable means to a supply line 325 (Fig. 40).

Air is supplied to the piston and cylinder device A for operating the infeed form pusher through a branch conduit 326 and through valves V-1 and V7. The valve V-1 has two operative positions and is controlled by solenoids S1 and S2. The solenoid S1, when energized, moves the valve to a position connecting the branch conduit 326 to a conduit 327 leading to the valve V7. When the valve is thus positioned, the conduit 45 to the rear end of the cylinder 42 is connected to drain. The solenoid S2, when energized, moves the valve V-1 to a position connecting the branch conduit 326 to the conduit 45 for admitting air under pressure to the rear end of the cylinder 42 for retracting the infeed pusher. In this position the valve connects conduit 327 to drain.

The valve V7 has two operative positions and is controlled by solenoids S14 and S15. When the solenoid

S14 is energized, the valve is moved to a position connecting the conduits 327 and 44 to admit air under pressure to the forward end of the cylinder 42 to move the infeed form pusher in a feed direction. It will be noted that operation of the piston and cylinder device A in this manner also requires that the valve V-1 be positioned to connect the branch conduit 326 and the conduit 327. The solenoid S15, when energized, moves the valve V7 to a position blocking the flow of fluid from the conduit 327 to the conduit 44, thereby to stop the feed movement of the infeed form pusher.

As described more in detail in describing the operation of the apparatus, the solenoids S1 and S14 may be energized by depressing a "Forward" push button on the control panel 175, which is illustrated in the wiring diagram. The solenoid S1 thereafter remains energized until all the columns in the supply area have been fed laterally into the processing alley. During this period, the solenoid S14 is intermittently energized; the solenoid S15 is energized as each successive column is positioned in the processing alley to stop the feed movement of the infeed pusher, and after the column in the infeed end of the alley has been moved to the revising area the solenoid S14 is again energized. After all the columns in the infeed area have been fed into the processing alley, the solenoid S2 may be energized under manual control of a "Reverse" switch illustrated in the wiring diagram and supported on the control panel 175.

Air under pressure is supplied to the piston and cylinder device B for operating the alley feed pusher through the supply line 325, a branch conduit 328, a branch conduit 329, and the valve V2. The valve V2 has two operative positions to which it is moved by solenoids S3 and S4, respectively. On energization of the solenoid S3, the valve is moved to a position to admit air under pressure to the right end of the cylinder 65 to effect movement of the alley feed pusher in a feed direction. When the valve is thus positioned, the conduit 87 leading from the left end of the cylinder is connected to drain through the valve V2. The solenoid S4, when energized, moves the valve to a position admitting fluid under pressure to the left end of the cylinder 65 to retract the alley feed pusher. When the valve is thus positioned, the conduit 86 leading from the right end of the cylinder is connected to drain. Energization of the solenoids S3 and S4 is obtained automatically, as described more in detail in describing the operation of the machine.

Air under pressure is supplied to the piston and cylinder device C for operating the clamping bar 96 through the supply line 325, branch conduit 328, a branch conduit 330, and valve V3. The valve V3 has two operative positions to which it is moved by solenoids S5 and S6, respectively. The solenoid S6 is energized to move the valve to a position admitting air under pressure to the upper end of the clamping cylinder 132 to effect movement of the clamping bar in a type gripping direction. In this position, the valve connects the lower end of the cylinder to drain. The solenoid S5, when energized, moves the valve V3 to a position admitting air under pressure to the lower end of the cylinder 132 and connecting the upper end of the cylinder to drain to effect movement of the clamping bar in a type releasing direction. As explained in describing the operation of the machine the solenoids S5 and S6 are both automatically energized.

Air under pressure is supplied to piston and cylinder device D for operating the lift apparatus for stripping removable lines, through the supply line 325, branch conduit 332, and valve V4. The valve V4 has two operative positions to which it is moved by solenoids S7 and S8. The solenoid S7 when energized, moves the valve to a position admitting air under pressure to the lower end of the cylinder 153, and connecting the upper

end of the cylinder to drain, to cause elevation of the type stripping apparatus. On energization of the solenoid S8, the valve is moved to a position connecting the upper end of the cylinder to the branch conduit 332 and connecting the lower end of the cylinder to drain. As explained in describing the operation, the solenoid S7 is energized automatically. The solenoid S8 is energized in response to depression of the "Down" buttons after the removable lines of type have been gathered 10 from the lifting apparatus.

Air under pressure is supplied to the piston and cylinder device E for operating the column severing pusher through the supply line 325, branch conduit 328, branch conduit 333, and valve V5. The valve V5 has two operative positions and is controlled by solenoids S9 and S10. The solenoid S9 is energized to move the valve to a position connecting the rear end of the cylinder 260 to air under pressure and connecting the forward end of the cylinder to drain to move the severing pusher in a feed direction. The solenoid S10 is energized to move the valve to a position connecting the rear end of the cylinder to pressure and the forward end to drain to retract the severing pusher. The solenoids S9 and S10 are energized under automatic control, as explained in 25 describing the operation.

Air under pressure is supplied to the piston and cylinder device F for operating the column spacer feed through the supply line 325, a branch conduit 334, and valve V6. Valve V6 has two operative positions to 30 which it is moved by solenoids S11 and S12. On energization of the solenoid S11, the valve is moved to a position admitting fluid under pressure to the right end of the cylinder 295 and connecting the left end of the cylinder to drain to move the spacer feed blade in a 35 feed direction. The solenoid S12 is energized to move the valve to a position admitting fluid under pressure to the left end of the cylinder and connecting the right end to drain to effect return movement of the column spacer feed blade. The solenoids S11 and S12 are energized under control of automatically operated means, as explained in describing the operation.

Electric circuit and operation

45 It is believed that the electric circuit for controlling operation of the apparatus, as illustrated in Fig. 39, will be best understood when described in connection with the operation of the machine. Accordingly, no separate detailed description of the circuit is given.

50 Let it be assumed that the machine is at rest, with each of the movable parts in their normal retracted positions, substantially as illustrated in Fig. 27, and with the electric circuits of Fig. 39 de-energized. The first step involved, of course, is to place in the infeed area 55 a five column type form used in printing a page of an information directory as illustrated in Fig. 27.

55 Referring now to Fig. 39, the electric circuit includes a pair of lines 340 and 341 connected with a suitable source of electric power. In operation, the electric circuit is energized by pressing a "Start" button illustrated 60 in the wiring diagram and mounted physically on the control panel 175 (Fig. 1). Depression of the "Start" switch completes a circuit from the line 340, through the "Start" switch, a wire 342, a holding coil 343, a wire 65 344, a wire 345 having a pair of "Stop" switches, and through the line 341 back to the source. Energization of the holding coil 343 effects closure of the contacts 343-1 to complete a holding circuit in parallel around the "Start" switch to maintain the coil 343 and the circuit in general energized until such time as the "Stop" 70 switch is opened to de-energize the circuit. Energization of the coil 343 also effects closure of its contacts 343-2 in a wire 346 to effect energization of a coil 347. The coil 347 represents the winding of a solenoid not otherwise illustrated, which is provided for controlling a

master valve in the air supply line 325 and which is held in the operative position so long as the electric circuit is energized, and which moves to a second position on de-energization of the electric circuit to exhaust air pressure from the air supply line 325 in order to relieve the fluid circuits of pressure fluid when the apparatus is not in operation.

Energization of the electric circuit as described above also completes a circuit from the wire 342 through a wire 349, a lamp or pilot light PL1 and the wire 345 to effect energization of the lamp to indicate that the circuit is energized.

In order to effect movement of the first column of type into the processing alley, as illustrated in Fig. 28, the "Forward" pushbutton switch is depressed to complete a circuit through the wire 342, the "Forward" switch, a wire 350, a wire 351, the solenoid S1 and the wire 345 to energize the solenoid S1. At the same time, a circuit is completed through the wire 350, solenoid S14, and a wire 353 to energize the solenoid S14.

Energization of the solenoids S1 and S14 effects movement of the valves V-1 and V7 to positions admitting fluid under pressure to the forward end of the infeed pusher cylinder to effect movement of the pusher in a feed direction.

On movement of the first column of type into the processing alley against the stop and guide member 55, as seen in Fig. 28, the column of type causes actuation of the limit switches LS1 and LS11, as illustrated diagrammatically in Fig. 40. Actuation of the limit switch LS1 in the manner described serves to close the circuit through each of its contacts LS1A and LS1B. Actuation of the limit switch LS11 in the manner described serves to close the circuit through the switch contacts LS11B.

Actuation of the limit switch LS1 in the manner described serves to stop the feed movement of the infeed alley pusher, by completing a circuit from the wire 342, through wire 355, contacts LS1A, a wire 356, the solenoid S15 and wire 353 to energize the solenoid. The solenoid S15 moves the valve V7 to a position blocking communication between the conduit 327 (Fig. 40) and the conduit 44 leading to the front end of the pusher cylinder. Accordingly, movement of the infeed pusher is stopped.

Closure of the limit switch LS1 in the manner described also serves to initiate movement of the alley feed pusher in a feed direction. This is accomplished by completing a circuit through the wire 342, wire 355, switch contacts LS1B, wire 358, switch contact LS11B, wire 359, limit switch LS15, solenoid S3, and wire 345 to energize the solenoid S3. At this time, the lift rails for stripping removable lines of type are in a retracted, down position, and the limit switch LS15 is closed as previously described. Energization of the solenoid S3 in the manner described effects movement of the valve V2 to a position admitting air under pressure to the right end of the pusher cylinder 65, initiating movement of the alley pusher in a feed direction.

In this instance, movement of the alley feed pusher continues through a complete feed stroke since there is no type in the alley ahead of the first column which is being pushed. At the end of a complete feed stroke (seen in Fig. 29), the limit switch LS2 (Fig. 40) is actuated by the alley pusher. At this time, since the column of type has been pushed from the infeed end of the processing alley, the limit switch LS1 returns to the open position illustrated in Fig. 39 so that a circuit is no longer completed to the solenoid S3. Actuation of the limit switch LS2 in the manner described effects return of the alley pusher by completing a circuit through the wire 342, a wire 361, a wire 362, a wire 363, switch contacts LS2A, and wire 364, the solenoid S4, and wire 345 to energize the solenoid S4. The solenoid moves valve V2 to a position admitting air under pressure to the left end of the pusher cylinder to retract the pusher to the starting position, as illustrated in Fig. 30. For the

time being, the alley feed pusher remains in the retracted position.

Actuation of the limit switch LS2 as previously described when the alley pusher reaches the end of the feed stroke, as illustrated in Fig. 29, also serves to initiate clamping action of the clamping anvil 95 and the clamping bar 96. This is accomplished by completing a circuit through the wire 342, the wire 361, the wire 362, wire 363, switch contacts LS2B, wire 366, wire 367, solenoid S16, wire 368, and the wire 345, to energize the solenoid S16. Energization of this solenoid, it will be recalled effects movement of the clamping anvil 95 to a type gripping position.

At the same time, a circuit is completed in similar manner through the wire 366, wire 370, solenoid S6 and wire 368 to energize this solenoid. Energization of the solenoid S6 moves the valve V3 to a position admitting air under pressure to the upper end of the clamping cylinder to effect movement of the clamping bar 96 to a type gripping position.

While the solenoids S6 and S16 are energized simultaneously, the solenoid S16 acts directly to move the cam bar 104 and clamping anvil 95, and the solenoid S16 acts indirectly through valve V3 and piston and cylinder device C to effect movement of the clamping bar 96. Thus, the anvil 95 moves into type gripping position first, and the bar 96 later moves against the other side of the column of type in the revising area to hold the column against the anvil, which defines the position of the type column.

As illustrated diagrammatically in Fig. 40, movement of the piston in the clamping cylinder 133 to its downward limit effects closure of the limit switch LS3. Actuation of the limit switch LS3 in the manner described is utilized to initiate upward movement of the lift rails to strip the removable lines of type from the column in the revising area. This is accomplished by completing a circuit through the wire 342, wire 361, limit switch LS3, wire 372, switch contacts D1 of a "Down" switch, wire 373, switch contacts D3 of another "Down" switch, wire 374, solenoid S7, wire 375, and wire 368 to energize the solenoid S7. The solenoid S7 moves the valve V4 to a position admitting air under pressure to the lower end of the lift cylinder to raise the lift rails. At the upper limit of its travel, the stripper stops and remains in this position, to permit the attendant to gather the removable lines of type for disposition, and the entire apparatus remains immobile during this period. After the removable lines of type have been gathered and disposed of, operation is resumed by manual depression of the "Down" pushbutton switches.

Two "Down" switches are provided in the circuit and are physically located on the control panel 175 (Fig. 1) at spaced positions. Both switches must be closed to continue operation of the apparatus, so that both hands of the operator are required to thereby positively avoid injury when operation is resumed.

Depression of the "Down" pushbutton switches effects return movement of the stripper to the lower limit of its travel by completing a circuit through the wire 342, a wire 377, switch contacts LS13B, a wire 378, "Down" switch D2, a wire 379, "Down" switch contacts D4, limit switch LS14, solenoid S8, and wire 375 to energize the solenoid S8. Energization of the solenoid S8 moves the valve V4 to a position admitting air under pressure to the upper end of the cylinder to cause return of the stripper downwardly to its rest position.

Movement of the lift cylinder downwardly is utilized to initiate release of the clamping means by the momentary actuation of limit switch LS4 during the downward stroke of the lift cylinder. Actuation of the switch LS4 in the manner described completes a circuit through the wire 342, switch LS4, wire 383, solenoid S5 and wire 368 to energize the solenoid S5. Energization of the solenoid S5 moves the valve V3 to a position admitting air under

pressure to the lower end of the clamping cylinder to break the toggle mechanism and withdraw the clamping bar 96 in a type releasing direction.

Movement of the piston in the clamping cylinder 132 in an upward direction as just described to withdraw the clamping bar 96 momentarily actuates the limit switch LS5, as previously described, and actuation of LS5 causes withdrawal of the clamping anvil 95 from the type gripping position. This is accomplished by means of a circuit through wire 342, limit switch LS4, wire 383, wire 384, limit switch contacts LS5B, solenoid S17, and wire 368 to energize the solenoid S17. While the limit switch LS4 is described as being momentarily closed, the arrangement of this switch and its actuator 141 is such that the switch is initially closed to initiate withdrawal of the clamping bar 96, and remains closed until such time as the switch LS5 is actuated, completing a circuit through LS4 and LS5B to energize the solenoid S17. The solenoid S17, when energized, moves the cam bar 104 in a direction to release the clamping anvil 95 for movement in a type releasing direction.

It will be clear from the description in the two preceding paragraphs that the clamping bar 96 is withdrawn from the type gripping position before the clamping anvil 95 is withdrawn.

Actuation of the switch LS5 on release of the toggle actuated clamping bar 96 as described above is utilized to initiate infeed motion of the infeed pusher to position a second column of type in the infeed end of the processing alley. This is accomplished by completing a circuit through the wire 342, the wire 361, limit switch contacts LS5A, limit switch contacts LS11A, a wire 386, limit switch LS12 and solenoid S14 to energize the solenoid. At this time, the limit switch LS12 is closed since the alley feed pusher is at rest at the end of its return stroke. Energization of the solenoid S14 in the manner described again moves the valve V7 to a position admitting air under pressure to the forward end of the infeed pusher cylinder to move the pusher in a rearward direction to feed a second column into the processing alley. Again, infeed movement of the pusher continues until such time as the column of type (the second column) engages the stop and guide member 55 as illustrated in Fig. 31. At the time the column of type engages the stop and guide member 55, the limit switches LS1 and LS11 are again actuated in the manner previously described to stop the infeed pusher, and to initiate feed movement of the alley feed pusher.

Feed motion of the alley feed pusher again continues through a complete feed stroke, as illustrated in Fig. 32, since the total length of the two columns of type in the processing alley is not sufficient to reach to the end of the processing alley. In the manner previously described, at the end of the alley pusher feed stroke, the limit switch LS2 is actuated to initiate return of the pusher to the rest position.

Actuation of the limit switch LS2 as described also functions to again initiate clamping of the type in the revising area which in turn initiates movement of the stripper upwardly to strip removable type from the column in the revising area.

Return movement of the lift cylinder downwardly, as previously described, must again be initiated by depression of the "Down" pushbutton switches. Movement of the lift cylinder downwardly initiates movement of the clamping means in a type releasing direction, as described in the previous cycle of operation.

Release of the clamping means again actuates the limit switch LS5 momentarily to again initiate feed motion of the infeed pusher to position a third column of type in the processing alley as illustrated in Fig. 33. Movement of the third column into the alley causes the pusher to stop and initiates movement of the alley feed pusher in a feed direction in the manner previously described. As illustrated in Figs. 33 and 34, the total length of the

columnar type in the processing alley at this time is such that the alley feed pusher cannot move through a complete feed stroke. Instead, the head of the column in the processing alley moves against the stop and guide member

- 5 208. At the time when the head of the column is moved against the guide 208, it will be recalled, the limit switch LS6 is actuated. In this case, actuation of the switch LS6 is utilized to initiate return movement of the alley pusher to the rest position illustrated in Fig. 34. This is accomplished by completing a circuit through the wire 342, the wire 361, wire 362, a wire 389, switch contacts LS7A, switch contacts LS6A, a wire 390, switch contact LS2A, wire 364, and the solenoid S4 to energize the solenoid. As previously described, energization of the solenoid S4 effects return movement of the alley feed pusher to the rest position illustrated in Fig. 34.

Actuation of the limit switch LS6 in the manner described also is utilized to initiate operation of the sensing apparatus to sense for multiple line listings. This is accomplished by completing a circuit through the wire 342, wire 362, wire 389, switch contacts LS7A, switch contacts LS7B, wire 392, and the solenoid S13 to energize the solenoid. The solenoid S13, when energized, functions to raise the left end of the sensing lever 220 (Fig. 19) to

- 20 25 sense for multiple line listings. If no multiple line listing is detected, energization of the solenoid S13 has no effect on the operation of the apparatus following.

If no multiple line listing is detected, after a suitable time delay to permit operation of the sensing mechanism, 30 closure of the limit switch LS6 is effective to initiate clamping in the manner previously described and also to initiate operation of the severing pusher 240 in a feed direction to sever a column length from the head of the column in the processing alley.

- 35 35 Clamping in response to actuation of the limit switch LS6 is initiated in the following manner. Closure of the limit switch LS6 completes a circuit through the wire 342, wire 362, wire 389, switch contacts LS7A, switch contacts LS6B, wire 394, wire 395, a timer relay coil 1TR and wire 368 to energize the timer relay. After a predetermined time delay to permit operation of the sensing mechanism, the timer relay contacts 1TR1 in wire 396 are closed to complete a circuit to the clamping solenoids S6 and S16 to effect movement of the clamping anvil and

40 45 the clamping bar in a type gripping direction. In the manner previously described, clamping movement is effective again to initiate upward movement of the stripper to strip the removable lines from the column in the revising area.

- 50 50 Actuation of the limit switch LS6 in the manner described initiates operation of the column severing pusher at the outfeed end of the processing alley, substantially as illustrated in Fig. 35, in the following manner. Closure of the limit switch LS6 completes a circuit through

55 55 the switch contacts LS6B, a wire 398, a wire 399 and a timer relay 2TR to energize the relay. After a time delay to permit operation of the sensing mechanism, the timer relay 2TR effects closure of its contacts 2TR1 in wire 398 to complete a circuit to the solenoid S9. Energization of the solenoid S9 moves the valve V5 to a position admitting air under pressure to the front end of the severing pusher cylinder to initiate movement of the cylinder rearwardly to sever the new column length.

- 60 65 As the severing column pusher moves the first column of type out of the processing alley, the column of type frees the follower 190 (Fig. 20), and the latter moves toward the right as illustrated in Fig. 35, into the recess 255 provided in the severing pusher. This permits the limit switch LS6 to open, thereby breaking the circuit to the solenoid S9. At the end of the feed stroke of the severing pusher, the limit switch LS6 is actuated.

Actuation of the limit switch LS8 initiates return of the severing pusher to the rest position by completing a circuit through the wire 342, limit switch LS8, wire 401,

and solenoid S10 to energize the solenoid. The solenoid S10 moves the valve V5 to a position admitting air under pressure to the rear end of the severing pusher cylinder causing return of the pusher to rest position, substantially as illustrated in Fig. 36.

Feed of column spacers into the composing area III is initiated upon actuation of the limit switch LS9 on the return stroke of the severing pusher. It will be recalled that the limit switch LS9 is momentarily actuated on the pusher return stroke. Closure of the switch LS9 completes a circuit through the wire 342, the wire 377, switch contacts LS13B, limit switch LS9 and a wire 407 to energize the solenoid S11. Energization of the solenoid S11 moves the valve V6 to a position admitting air under pressure to the right end of the spacer feed cylinder.

At the end of the spacer feed stroke, the limit switch LS10 is actuated by the spacer feed pusher. This completes a circuit through wire 341, wire 361, wire 362, wire 363, and limit switch LS10 to energize the solenoid S12. Energization of solenoid S12 moves the valve V6 to a position admitting air under pressure to the left end of the spacer feed cylinder to return the spacer feed blade to the rest position.

Since, at this time, the lift cylinder is positioned at the upper limit of its travel, operation of the machine may be resumed only on depression of the "Down" pushbutton switches in the manner previously described.

In the event that the sensing apparatus detects a multiple line listing, solenoid S13, upon energization as previously described, will move the left end of the lever 220, as viewed in Fig. 19, upwardly to a position causing actuation of the limit switch LS7. Actuation of the switch LS7 in the manner described causes opening of the contacts LS7A and closing of the contacts LS7B. Opening of the switch contacts LS7A breaks the circuit through the closed limit switch LS6, so that neither clamping of the type in the revising area nor severing of the type at the head of the processing alley will follow automatically. Instead, the apparatus is effectively disabled. At the same time, closure of the contacts LS7B completes a circuit through these contacts, through a wire 403 and a lamp or pilot light PL2 to energize the light. Energization of the light indicates to the operator that a multiple line listing has been sensed and that this situation must be corrected.

Once informed of the multiple line listing, the machine operator depresses the reset button 235 illustrated in Fig. 19 to reset the limit switch LS7 to open the contacts LS7B and close the contacts LS7A. At the same time, the operator manually depresses the left end of the sensing lever 220, as viewed in Fig. 19, to prevent reactivation of the limit switch LS7. This results in again initiating operation of the apparatus, since the circuits are completed through limit switches LS7 and LS6 to initiate clamping and severing in the manner described previously. Accordingly, clamping, stripping of the removable type, and severing of the new column length follow automatically. After the removable lines are stripped and the column length is severed, the operator removes the leading line of the multiple line listing from the foot of the severed column and replaces this line with a blank slug. Then, the leading line of the multiple line listing is inserted at the head of the column in the processing alley. As the machine is disabled until such time as the "Down" pushbutton switches are depressed to again initiate operation, the operator is enabled to reposition the lead line of the multiple line listing without danger of injury.

After the lead line of the multiple line listing is properly repositioned, and the removable lines of type gathered for disposition, operation of the apparatus may be resumed in the manner previously described by manual depression of the "Down" button.

In the operation described hereinabove, return movement of the lift cylinder in a downward direction initi-

ated operation of the clamping means to release the type in the revising area of the alley, and also to initiate operation of the infeed pusher to push a succeeding column of type into the processing area. However, under the present circumstances a portion of the third column of type from the infeed area still remains in the infeed end of the processing alley as illustrated in Fig. 35. Accordingly, the infeed pusher cannot be operated to push a succeeding column into the alley. This condition is indicated in the circuit by reason of the fact that the alley feed pusher has not completed a full feed stroke to reset the limit switch LS11 to the position closing contacts LS11A. Consequently, the limit switch LS11 is positioned with the contacts LS11A open and the contacts LS11B closed. Since the contacts LS11A are open, no circuit can be completed through the solenoid S14 to effect operation of the infeed pusher.

Instead, a circuit is completed through the wire 342, the wire 361, the limit switch contacts LS5A, which are momentarily closed on release of the clamping means, switch contacts LS11B, wire 359, limit switch LS15 which is closed on return of the stripper to the "Down" position, and solenoid S3 to initiate operation of the alley feed pusher. At this time, as illustrated in Fig. 36, the type in the processing alley ahead of the alley pusher is such that the pusher is enabled to complete a full feed stroke, actuating the limit switch LS2 in the manner previously described to cause return movement of the pusher to the rest position illustrated in Fig. 37.

In the event that only the limit switch LS2 is actuated at the end of the pusher feed stroke, and the head of the column in the processing alley does not reach to the end of the alley to actuate the limit switch LS6, clamping and stripping of the removable type follow in the manner described hereinabove. In the event that both the limit switch LS2 and the limit switch LS6 are simultaneously actuated, clamping, stripping, sensing, and severing will follow. In the event that only the limit switch LS6 is closed, clamping, stripping, sensing and severing will occur in the manner previously described.

Upon again initiating operation of the apparatus on depression of the "Down" buttons, the infeed pusher will again be operated, instead of the alley feed pusher, to position the fourth column of type from the infeed area into the processing alley, as illustrated in Fig. 8.

The description of the operation given hereinabove is believed to cover every possible order and sequence of operation. The remaining operation of the apparatus until such time as the tray in the composing area is filled will be repeats of one or more of the operations described hereinabove. When the tray in the composing area III is filled, the limit switch LS13 will be actuated to open the contacts LS13B and to close the contacts LS13A. Opening the contacts LS13B prevents further operation of the apparatus, and closure of the contacts LS13A completes a circuit through the wire 377, contacts LS13A, a wire 405 and the wire 375 to energize the pilot light PL3 to indicate to the attendant that the filled tray must be removed and an empty replaced in the composing area. When the new tray is placed in the composing area, the limit switch LS13 is reset, and the "Down" pushbuttons are depressed to again initiate automatic operation of the apparatus.

When the supply of type in the infeed area of the machine is depleted, a new form is placed in the infeed area, and at the proper time the "Reverse" pushbutton switch is depressed to retract the infeed pusher to the starting position. Closure of the reverse switch completes a circuit through the wire 342, the reverse switch, a wire 406, and the solenoid S2 to energize this solenoid. Energization of the solenoid S2 moves the valve V-1 to a position admitting air under pressure to the forward end of the infeed pusher cylinder to retract the pusher to the starting position.

While the machine has been illustrated and described for use in connection with type columns and forms of particular lengths including lines of type of particular lengths, it will be appreciated that the machine is not necessarily limited to such a use, but by virtue of the various adjustments provided, may be adapted for use with column length and line lengths which differ from those described and illustrated.

The term "side-by-side" is used herein with respect to lines of type to define the relative positions of lines in a single column; while with respect to separate columns, it is used to define the normal relative positions of the columns in a page.

The "removable lines," or slugs, RM, and columns or pages including such removable lines or slugs, not claimed per se herein, are described and claimed in our copending application 664,579, filed June 10, 1957.

The foregoing detailed description is given for clearness of understanding only and no unnecessary limitations should be understood therefrom, as modifications will be obvious to those skilled in the art.

We claim:

1. In a method of revising type in columnar form consisting of retainable and removable lines of type arranged side by side on edge, the steps comprising: placing a column of type on a plane surface in a revising area; clamping the type in the column by lateral pressure bearing only on the ends of the retainable lines; lifting the removable lines to a plane above the retainable lines by engaging portions of the removable lines which extend laterally beyond the ends of the retainable lines; gathering the removable lines for disposition; and releasing the lateral pressure on the retainable lines.

2. In a method of revising type in columnar form consisting of columns of type of predetermined length arranged side by side, said columns containing retainable and removable lines of type and there being column spacers between adjacent columns, the steps comprising: placing the type form on a plane surface, sliding the form laterally to position the first column in a processing alley and a spacer alongside the alley; sliding said first column longitudinally of the alley to a revising area; sliding the column spacer endwise from the position alongside the processing alley; lifting the removable lines of type from the first column to a plane above the retainable lines; sliding the type form laterally to position the second column in the processing alley, sliding the revised first column and the second column longitudinally to move the revised column out of the revising area and to position the second column in the revising area.

3. In a method of revising type in columnar form consisting of columns of type arranged side by side, said columns containing retainable lines of type and at least some columns containing removable lines of type, the steps comprising: placing the type form on a plane surface, sliding the first column of the type form laterally into a processing alley; sliding said first column longitudinally along the alley to a revising area; clamping the type in the first column by lateral pressure bearing only on the retainable lines; lifting the removable lines from the first column to a plane above the retainable lines by engaging portions of the removable lines which extend laterally beyond the ends of the retainable lines; gathering the removable lines for disposition; releasing lateral pressure on the retainable lines; sliding the second column of the form laterally into the processing alley; sliding the revised first column and the second column longitudinally along the alley to place the second column in the revising area and to place the first column in an out-feed area; and severing from the type in the out-feed area a column length containing a predetermined number of lines of type by sliding said predetermined lines laterally out of the alley.

4. In a method of revising type in columnar form consisting of columns of type arranged side by side, said

columns containing retainable lines of type and removable lines of type, the steps comprising: placing the type form on a plane surface; sliding the first column of the type form laterally into a processing alley; sliding said first column longitudinally along the alley to a revising area; lifting the removable lines of type from the first column to a plane above the retainable lines; sliding a second column of the type form laterally into the processing alley; sliding the revised first column and said second column longitudinally along the alley to place the second column in the revising area and the first column in an out-feed area; severing from the column in the out-feed area a column length containing a predetermined number of lines by sliding said predetermined lines laterally out of the alley; and sliding a column spacer endwise into position between the severed column length and the alley.

5. In a method of converting type in columnar form of a first predetermined length to type in columnar form

20 of a second predetermined length, said columnar form comprising a plurality of lines of the type arranged side by side on edge, the steps comprising: placing columns of said first length side by side on a plane surface; sliding said columns in entirety laterally to position the first column in a feed alley; sliding said first column longitudinally along said feed alley; again sliding the remaining columns laterally to place the second column in the feed alley behind the first column to form an elongated column; sliding the elongated column longitudinally along the feed alley to position the forward portion of said column in an out-feed area; and severing from the portion of the column in the out-feed area a column segment of said second predetermined length by sliding such column segment laterally out of the alley.

6. In a method of revising columns of type of a first

35 predetermined length arranged side by side with column spacers between adjacent columns, and converting to columns of type of a second predetermined length arranged in side by side relation with column spacers between adjacent columns, the steps comprising: sliding the columns of said one predetermined length laterally to position the first column thereof in a feed alley; sliding said first column longitudinally along the alley; sliding the column spacer endwise from the position between the second column and the feed alley; again sliding the remaining columns of said one predetermined length laterally to position the second column in the feed alley behind the first column to form an elongated column; sliding the column longitudinally along the feed alley to position the forward portion of said column in an out-feed

40 area; severing from the elongated portion of the column in the out-feed area a column segment of said second predetermined length by sliding such column laterally out of the alley; and sliding a column spacer of said second predetermined length endwise into position between the severed column length and the alley.

7. In a method of reorganizing a columnar type form to change the length of the columns, the steps comprising:

45 pushing the columns longitudinally along a guide alley in head to foot relationship with the lines at the head of the column in the lead to carry the forward portion of the column into an out-feed area; sensing when a line of type in the guide alley at the margin of the out-feed area has no type face at one margin; severing from the type in the out-feed area a column length containing a predetermined number of lines of type; and removing from the severed column length the lines from the foot up to and including the last line from the head which has type face at said one margin and placing the same in the lead position in the guide alley.

8. In a type form revising apparatus, in combination: means for supporting a column of type consisting of a plurality of lines of type arranged side by side on edge and including retainable lines of a predetermined length and removable lines of a lesser predetermined length

having lifting lugs at the top which project laterally beyond the ends of the retainable lines; means for pushing the column endwise on the supporting means into a revising area; clamping means at the revising area including rails for exerting lateral pressure against opposite sides of the column below the lifting lugs to clamp the retainable lines in position; lifting bars flanking the column above the clamping rails so that the lifting lugs on removable lines of a column in the revising area overlie the lifting bars; means for raising the lifting bars to lift the removable lines from the column to an area above the retainable lines for disposition; and means for actuating the clamping means to release the retainable lines, said column pushing means being actuatable to push the revised column endwise from the revising area.

9. In a type form revising apparatus, in combination: means for positioning seriatim in a clamping and lifting area, columns of type which include retainable and removable lines of type; means for selectively clamping the retainable lines of type in a column by exerting pressure laterally on the ends thereof while leaving the removable lines of type free of lateral pressure, said clamping means comprising a clamping anvil engageable with the ends of the retainable lines of type at one side of the column, a clamping bar movable toward and away from the other side of the column, a toggle linkage having one end fixed and the other end connected to the movable clamping bar for moving the same, and means connected to the knee of the toggle linkage for making and breaking the toggle; and means for lifting only the removable lines to an area above the retainable lines for disposition.

10. In a type form revising apparatus, in combination, means for positioning seriatim in a clamping and lifting area, columns of type which include retainable and removable lines of type; means for selectively clamping the retainable lines of type in a column by exerting pressure laterally on the ends thereof while leaving the removable lines of type free of lateral pressure, said clamping means comprising a clamping bar releasably engageable with the ends of the retainable lines of type at one side of the column, a clamping anvil movable toward and away from the ends of the retainable lines at the other side of the column, said anvil having a cam surface on one side opposite the type engaging side, means biasing the anvil in a type releasing direction, a cam member movable relative to the anvil and having a cam surface engageable with the cam surface on the anvil, and means for moving the cam member to actuate the clamping anvil in timed relationship with the clamping and release of the clamping bar; and means for lifting only the removable lines to an area above the retainable lines for disposition.

11. In a type form revising apparatus, in combination: means for positioning seriatim in a clamping and lifting area, columns of type which include retainable and removable lines of type; a clamping bar reciprocable toward and away from one side of the column; a toggle linkage operatively connected to said clamping bar; piston and cylinder means acting on the toggle linkage for extending and contracting the toggle to reciprocate the clamping bar; a clamping anvil reciprocable transversely against the other side of the column, said anvil having a wedge-shaped cam surface on the side away from the column; a cam bar slidable longitudinally in contact with said cam surface; solenoid means for sliding said cam bar to reciprocate the anvil; means biasing the anvil away from the column; control means for actuating said piston and cylinder means and said solenoid means in timed relationship to selectively clamp and release a column of type; and means for lifting only the removable lines of type to an area above the retainable lines when the column is clamped.

12. In a type form revising apparatus, in combination: means for positioning seriatim in a clamping and lifting area, columns of type including retainable and removable lines of type; means for selectively clamping the

retainable lines of type in a column by exerting pressure laterally on the ends of said lines while leaving the removable lines of type free of lateral pressure; means for lifting only the removable lines to an area above the retainable lines for disposition, actuating means for the lifting means; means responsive to movement of the clamping means to clamp position for energizing the actuating means automatically to lift the removable lines; and manually operable means for energizing said actuating means to return the lifting means.

13. In a type form revising apparatus, in combination: means for supporting columns of type consisting of lines of type arranged side by side on edge and including retainable and removable lines of type; pusher means for sliding the columns seriatim in head to foot relationship into a clamping and lifting area; means for selectively clamping retainable lines of type in the columns by exerting pressure laterally on the ends thereof while leaving the removable lines of type free of lateral pressure; means for lifting only the removable lines to an area above the retainable lines for gathering of the removable lines; means for releasing the clamping means to free the retainable lines; and pusher actuating means responsive to release of the clamping means to slide the retainable lines in columnar form to close the gaps left by the removable lines and to slide the revised lines from the clamping and lifting area.

14. In a type form composing apparatus: a planar table having an in-feed area of a width for supporting a type form consisting of a plurality of columns of type arranged side by side and a processing alley alongside the in-feed area having a width approximately equal to the width of a column of type; said columns of type each comprising a plurality of lines of type arranged side by side on edge, in-feed means for moving complete columns of type laterally into the processing alley one at a time; pusher means for pushing each column and successive columns one behind the other longitudinally along the alley at right angles to the movement from the in-feed area; driving means for extending and retracting the pusher means, and means for preventing actuation of the in-feed means when the pusher means is extended.

15. In a type form composing apparatus: a planar table having an in-feed area of a width for supporting a type form consisting of a plurality of columns of type arranged side by side, said columns of type each comprising a plurality of lines of type arranged side by side on edge, said table also having a processing alley alongside the in-feed area; in-feed means for pushing the entire type form laterally to successively position the type columns in the processing alley; means for pushing the columns successively longitudinally along the processing alley, and means responsive to the presence of type in the processing alley at a position blocking lateral movement of the type form for preventing actuation of the in-feed means.

16. In a type form composing apparatus: a table having an in-feed area for supporting type in columnar form consisting of a plurality of columns of type arranged side by side with column spacers between adjacent columns, said table also having a processing alley alongside the in-feed area; means for moving the type form laterally to successively position the type columns thereof in the processing alley; a reciprocal pusher for sliding the columns successively longitudinally along the processing alley; and a movable hook member on the pusher for engaging the forward end of a column spacer at the end of a column pushing stroke and pulling the spacer endwise rearwardly on the pusher return stroke out of position between the processing alley and the next column in the form.

17. In a type form composing apparatus: a table having an in-feed area for supporting type in columnar form consisting of columns of type arranged side by side with column spacers between adjacent columns, said table also having a processing alley alongside the in-feed area; means

for moving the type form laterally to successively position the type columns thereof in the processing alley; a reciprocal pusher for sliding the columns successively longitudinally along the processing alley; a pivoted latch finger engageable with the column spacer which is exposed when a preceding column is pushed along the alley; and a movable hook member on the pusher for engaging the forward end of a column spacer at the end of a column pushing stroke and pulling the spacer endwise rearwardly on the pusher return stroke out of position between the processing 10 alley and the next column in the form.

18. In a type form composing apparatus: a table having an in-feed area of a width for supporting type in columnar form consisting of columns of type arranged side by side with column spacers between adjacent columns, said columns of type each comprising a plurality of lines of type arranged side by side on edge, said table also having a processing alley alongside the in-feed area; means for moving the entire type form laterally to successively position the type columns thereof in the processing alley; a reciprocal pusher for sliding the columns successively longitudinally along the processing alley; and a pivoted latch finger independent of the pusher engageable with the column spacer exposed when a preceding column is pushed forwardly in the alley for holding the spacer upright on edge.

19. In a type form composing apparatus, in combination: a planar table having an in-feed area for supporting type in columnar form and a processing alley alongside the in-feed area; said columnar form comprising a plurality of lines of type arranged side by side on edge; means for pushing a column of type in entirety laterally from the in-feed area into the processing alley; switch means operable by the type column on movement into the processing alley; and means energized on operation of the switch means for pushing the column of type longitudinally along the processing alley.

20. In a type form composing apparatus, in combination: a planar table having an in-feed area for supporting type in columnar form and a processing alley alongside the in-feed area including an upright column guide surface opposite the in-feed area; said columnar form comprising a plurality of lines of type arranged side by side on edge; means for moving a column of type as an entity laterally from the in-feed area into the processing alley against said guide surface; switch means positioned adjacent the guide surface and operable by the side of the column of type when the latter contacts the guide surface; and means energized by operation of said switch means for pushing the column on the table longitudinally along the processing 50 alley.

21. In a type form composing apparatus, in combination: a table having an in-feed area of a width for supporting type in columnar form consisting of columns of type side by side, said columns of type each comprising a plurality of lines of type side by side on edge, said table having a processing alley alongside the in-feed area; guide means adjustably spaced on the table in said infeed area defining an infeed channel of adjustable width for type forms of various lengths; a feed bar of adjustable length to conform to the channel width for pushing the entire type form laterally along the channel to position the first column of the form in the alley, drive means for moving the feed bar along the channel; and means operable by the type column on movement into the processing alley 65 to de-energize said drive means.

22. In a type form composing apparatus, in combination: a table having an in-feed area of a width for supporting type in columnar form consisting of columns of type side by side, said columns each comprising a plurality of lines of type arranged side by side on edge, said table having a processing alley alongside the in-feed area; a feed bar for pushing the complete type form laterally to position the first column of the form in the processing alley; drive means for actuating the feed bar; switch means

operable by the presence of the type column in the processing alley to de-energize said drive means; and means energized by operation of said switch means to push the column longitudinally along the processing alley.

23. In a type form composing apparatus: a table having an in-feed area for supporting a type form; a pair of parallel guide bars forming with the table top a slideway for guiding movement of the type form; a feed bar carrier reciprocable along the slideway, a depending feed bar pivotally mounted on the carrier and engageable with a form in the slideway to push the form forwardly along the slideway; cooperating means on the carrier and feed bar to prevent rearward swinging movement of the feed bar on forward movement of the carrier; guide means adjacent the forward end of the slideway to pivot the feed bar forwardly and upwardly to a generally horizontal position on rearward movement of the carrier to pass over type during return movement; means to retain the feed bar in the horizontal position during return movement of the carrier; and means permitting return pivotal movement of the feed bar downwardly and rearwardly to the depending position at the end of the carrier return stroke.

24. In a type form composing apparatus: a table having an in-feed area for supporting a type form; a pair of parallel guide bars forming with the table top a slideway for guiding movement of the type form; a feed bar carrier reciprocable along the slideway; a depending feed bar pivotally mounted on the carrier and engageable with a form in the slideway to push the form forwardly along the slideway; cooperating means on the carrier and feed bar to prevent rearward swinging movement of the feed bar on forward movement of the carrier; a laterally projecting guide pin on the feed bar at one end near the bottom; a guide track for the guide pin in the adjacent guide bar including a lower horizontal run permitting forward travel of the feed bar with the carrier; a pivoted gate member adjacent the forward end of the lower run permitting movement of the guide pin past the gate and having an upwardly and rearwardly inclined cam surface engageable by the guide pin for pivoting the feed bar forwardly and upwardly to a generally horizontal position on rearward movement of the carrier to pass over type during return movement; an upper horizontal run for the guide pin permitting return of the feed bar with the carrier; and an upright slot connecting the upper and lower runs at the rear end to permit return pivotal movement of the feed bar downwardly and rearwardly to the depending position at the end of the carrier return stroke.

25. In a type form composing apparatus for use in revising type in columnar form consisting of lines of type arranged side by side on edge, in combination: means including a table top forming a processing alley for slidably supporting a column of type for movement from an in-feed end of the alley toward an out-feed end of the alley, said table top being inclined downwardly from the in-feed end toward the out-feed end; pusher means for sliding the column of type from the in-feed end toward the out-feed end including, a pusher block movable forwardly along the processing alley from a starting position at the in-feed end of the alley toward the out-feed end and back to starting position, and a column pusher element resiliently supported on the forward end by the pusher block, extending transversely of the processing alley immediately above the table top to yieldably engage the last line of type in the column near the bottom edge of the line only to push the column forwardly without tipping the lines of type in the column forwardly; and means for reciprocating the pusher block.

26. In a type form revising apparatus: a planar table having an out-feed area for supporting type in columnar form consisting of lines of type arranged side by side on edge; means for pushing columns of type on the table longitudinally one after another into the out-feed area; a stop member engageable by the head of the column moved

into the out-feed area to limit further movement of the column; a severing bar having a length for severing from the column in the out-feed area a column length containing a predetermined number of lines by pushing such column length on the table laterally from the out-feed area.

27. In a type form composing apparatus: a table having an out-feed area for supporting type in columnar form consisting of lines of type arranged side by side on edge; means for pushing columns of type longitudinally one after another into the out-feed area; a stop member engageable by the head of a column moved into the out-feed area to limit further movement of the column; a severing bar for severing from the head of the column in the out-feed area a column length containing a predetermined number of lines by pushing such column length laterally out of the out-feed area; means for reciprocating the severing bar through feed and return strokes; means for supporting a supply of column spacers; and a column spacer feed member actuated automatically on return of the severing pusher bar to feed a column spacer endwise between the severed column length and the out-feed area.

28. In a type form composing apparatus: a table having an out-feed area and an adjacent composing area for supporting type in columnar form consisting of lines of type arranged side by side on edge; means for pushing columns of type longitudinally one after another into the out-feed area; a stop member engageable by the head of a column moved into the out-feed area to limit further movement of the column; first switch means operable by the head of the column on abutting the stop member; reciprocal severing bar means energized by operation of said switch means to sever a column length containing a predetermined number of lines by pushing such column length laterally out of the out-feed area into the composing area; second switch means operable by said out-feed bar means on return to starting position; means for supporting a supply of column spacers; and a feed member energized by operation of said second switch means to feed a column spacer endwise between the out-feed area and the severed column length in the composing area.

29. In a type form composing apparatus: a table having a processing alley and a composing area alongside the processing alley for supporting a tray into which type in columnar form may be pushed laterally from the processing alley; said columnar form comprising a plurality of lines of type arranged side by side on edge; means for pushing columns of type longitudinally one after another along the processing alley; out-feed bar means having a length for severing from the head of the column in the processing alley a column length containing a predetermined number of lines by pushing such column length laterally out of the processing alley into the tray; and signal means for indicating the presence of a predetermined number of severed column lengths side by side in the tray.

30. In a type form composing apparatus, in combination: a table having an out-feed area for supporting type in columnar form consisting of lines of type arranged side by side on edge; means for pushing columns of type longitudinally one after another into the out-feed area; reciprocal out-feed means for severing from the columnar type in the out-feed area a column length having a predetermined number of lines of type by pushing such column length laterally from the out-feed area; a normally inoperative sensing member movably mounted adjacent the out-feed area; means for moving the sensing member to sense the marginal portion of the first line of type in the out-feed area after said predetermined number of lines to determine whether there is type face in said marginal portion; and means responsive to movement of the sensing member in the absence of type face in said marginal portion to indicate such condition and to disable the apparatus prior to reciprocation of the out-feed means.

31. In a semi-automatic apparatus for revising a pre-

pared type form consisting of columns of type of one predetermined length side by side and converting to a revised type form consisting of columns of type of another predetermined length side by side: a planar table having a processing alley including an in-feed end and an out-feed end, a supply area for a prepared type form alongside the in-feed end of the processing alley, and a composing area alongside the out-feed end of the processing alley; in-feed means for moving a prepared form laterally in the supply area to successively position columns of the prepared form in the processing alley; feed means reciprocal through feed and return strokes for pushing columns of type longitudinally along the alley from the in-feed end toward the out-feed end; means actuated by movement of a column into the alley to actuate the feed means through a feed stroke; means for actuating the feed means through a return stroke; means for actuating the in-feed means to advance a succeeding column into the alley on movement of the preceding column out of the in-feed end of the alley; reciprocal out-feed means for severing from the column at the out-feed end of the alley a column length of said other predetermined length by moving such column length laterally from the alley into the composing area; and means actuated on arrival of the head of the column in the processing alley at a predetermined position to energize the out-feed means.

32. In a semi-automatic apparatus for revising a prepared type form consisting of retainable lines and removable lines arranged in columns of one predetermined length side by side, and converting to a revised type form consisting only of retainable lines in columns of another predetermined length side by side: a planar table having a processing alley including an in-feed end, an out-feed end and a processing area therebetween, a supply area for a prepared type form alongside the in-feed end of the processing alley, and a composing area alongside the out-feed end of the processing alley; in-feed means for moving a prepared form in the supply area laterally to position a first column of the prepared form in the processing alley; feed means reciprocal through feed and return strokes for pushing columns of type longitudinally along the alley from the in-feed end to the processing area and from the processing area to the out-feed end; means actuated by movement of a column into the alley to energize the feed means through a feed stroke; means for energizing the feed means through a return stroke; means for selectively clamping the retainable lines of type in the processing area by exerting pressure laterally on the ends thereof while leaving the removable lines of type in the processing area free of lateral pressure; means responsive to said clamping for lifting only the removable lines of type in the processing area to positions above the retainable lines for disposition; means for actuating the in-feed means to advance a succeeding column laterally into the alley on movement of the preceding column longitudinally out of the in-feed end of the alley into the processing area of the alley; manually operable means for initiating return of the lifting means to rest position; means responsive to return of the lifting means to rest for releasing clamping pressure and for again initiating operation of the feed means to push a succeeding column of the prepared form longitudinally in the processing alley from the in-feed end to the processing area; and reciprocal out-feed means actuated on arrival of the head of the column at a predetermined position in the processing alley for severing from the column at the out-feed end of the alley a column length of said other predetermined length by moving said column length laterally from the alley into the composing area.

33. In a semi-automatic apparatus for revising a prepared type form consisting of columns of type of one predetermined length side by side with column spacers between adjacent columns, and converting to a revised type form consisting of columns of type of another predetermined length side by side: a planar table having a

processing alley including an in-feed end and an out-feed end, a supply area for a prepared type form alongside the in-feed end of the processing alley, and a composing area alongside the out-feed end of the processing alley; in-feed means for moving a prepared form laterally in the supply area to successively position columns of the prepared form in the processing alley; feed means reciprocal through feed and return strokes for pushing columns of type longitudinally along the alley from the in-feed end toward the out-feed end; means actuated by movement of a column into the alley to actuate the feed means through a feed stroke; means for actuating the feed means through a return stroke; a hook on the feed means for engaging the end of a column spacer between the alley and the next column in the supply area to remove the spacer on the return stroke; means for actuating the in-feed means to advance a succeeding column into the alley on movement of the preceding column out of the in-feed end of the alley; reciprocal out-feed means for severing from the column at the out-feed end of the alley a column length of said other predetermined length by moving such column length laterally from the alley into the composing area; and means actuated on arrival of the head of the column in the processing alley at a predetermined position to energize the out-feed means.

34. In a semi-automatic apparatus for revising a prepared type form consisting of columns of type of one predetermined length side by side with column spacers between adjacent columns, and converting to a revised type form consisting of columns of type of another predetermined length side by side with column spacers between adjacent columns: a planar table having a processing alley including an in-feed end and an out-feed end, a supply area for a prepared type form alongside the in-feed end of the processing alley, and a composing area alongside the out-feed end of the processing alley; in-feed means for moving a prepared form laterally in the supply area to successively position columns of the prepared form in the processing alley; feed means reciprocal through feed and return strokes for pushing columns of type longitudinally along the alley from the in-feed end toward the out-feed end; means actuated by movement of a column into the alley to actuate the feed means through a feed stroke; means for actuating the feed means through a return stroke; a hook on the feed means for engaging the end of a column spacer between the alley and the next column in the supply area to remove the spacer on the return stroke; means for actuating the in-feed means to advance a succeeding column into the alley on movement of the preceding column out of the in-feed end of the alley; reciprocal out-feed means for severing from the column at the out-feed end of the alley a column length of said other predetermined length by moving such column length laterally from the alley into the composing area; means actuated on arrival of the head of the column in the processing alley at a predetermined position to energize the out-feed means through feed and return strokes; and spacer feed means actuated at the end of the return stroke of the out-feed means to position a column spacer between the processing alley and the adjacent column in the composing area.

35. In a semi-automatic apparatus for revising a prepared type form consisting of columns of type of one predetermined length side by side, and converting to a revised type form consisting of columns of type of another predetermined length side by side with column spacers between adjacent columns: a planar table having a processing alley including an in-feed end and an out-feed end, a supply area for a prepared type form alongside the in-feed end of the processing alley, and a composing area alongside the out-feed end of the processing alley; in-feed means for moving a prepared form laterally in the supply area to successively position columns of the prepared form in the processing alley; feed means

reciprocal through feed and return strokes for pushing columns of type longitudinally along the alley from the in-feed end toward the out-feed end; means actuated by movement of a column into the alley to actuate the feed means through a feed stroke; means for actuating the feed means through a return stroke; means for actuating the in-feed means to advance a succeeding column into the alley on movement of the preceding column out of the in-feed end of the alley; reciprocal out-feed means

5 for severing from the column at the out-feed end of the alley a column length of said other predetermined length by moving such column length laterally from the alley into the composing area; means actuated on arrival of the head of the column in the processing alley at a predetermined position to energize the out-feed means through feed and return strokes; and spacer feed means actuated at the end of the return stroke of the out-feed means to position a column spacer between the processing alley and the adjacent column in the composing area.

10 36. In a semi-automatic apparatus for revising a prepared type form consisting of columns of type of one predetermined length side by side and converting to a revised type form consisting of columns of type of another predetermined length side by side: a planar table

15 having a processing alley including an in-feed end and an out-feed end, a supply area for a prepared type form alongside the in-feed end of the processing alley, and a composing area alongside the out-feed end of the processing alley; in-feed means for moving a prepared

20 form laterally in the supply area to successively position columns of the prepared form in the processing alley; feed means reciprocal through feed and return strokes for pushing columns of type longitudinally along the alley from the in-feed end toward the out-feed end; means

25 actuated by movement of a column into the alley to actuate the feed means through a feed stroke; means for actuating the feed means through a return stroke; means for actuating the in-feed means to advance a succeeding column into the alley on movement of the preceding

30 column out of the in-feed end of the alley; reciprocal out-feed means to sever from the column at the out-feed end of the alley a predetermined number of lines of type to form a column of said other predetermined length and move it laterally into the composing area; means for

35 sensing a marginal portion of the first line of type in the alley which is not in said predetermined number of lines to determine whether there is a type face in said marginal portion; and means responsive to the absence of a type face in said marginal portion to disable the appa-

40 ratus prior to reciprocation of the out-feed means.

37. In a semi-automatic apparatus for revising a prepared type form consisting of columns of type of one predetermined length side by side and converting to a revised type form consisting of columns of type of another predetermined length side by side: a planar table

45 having a processing alley including an in-feed end and an out-feed end, a supply area for a prepared type form alongside the in-feed end of the processing alley, and a composing area alongside the out-feed end of the pro-

50 cessing alley; in-feed means for moving a prepared form laterally in the supply area to successively position columns of the prepared form in the processing alley; feed means reciprocal through feed and return strokes for pushing columns of type longitudinally along the alley

55 from the in-feed end toward the out-feed end; means actuated by movement of a column into the alley to actuate the feed means through a feed stroke; means for actuating the feed means through a return stroke; means for actuating the in-feed means to advance a suc-

60 ceeding column into the alley on movement of the preceding column out of the in-feed end of the alley; reciprocal out-feed means for severing from the column at the out-feed end of the alley a column length of said other predetermined length by moving such column length laterally from the alley into the composing area; means

65 70 75

actuated on arrival of the head of the column in the processing alley at a predetermined position to energize the out-feed means through feed and return strokes; and means responsive to the presence of a predetermined number of columns in the composing area for disabling the apparatus.

38. In an apparatus for revising a prepared type form consisting of columns of type of one predetermined length side by side and converting to a revised type form consisting of columns of type of another predetermined length side by side: a planar table having an alley including an in-feed end and an out-feed end, a supply area for a prepared type form alongside the in-feed end of the alley, and a composing area alongside the out-feed end of the alley; in-feed means for moving a prepared form laterally in the supply area to successively

position columns of the prepared form in the alley; feed means reciprocal through feed and return strokes for pushing columns of type longitudinally along the alley from the in-feed end toward the out-feed end; and reciprocal out-feed means for severing from the column at the out-feed end of the alley a column length of said other predetermined length by moving such column length laterally from the alley into the composing area.
